Fig. 2 -

Diagram illustrating two sections, A and B, of a control circuit. The circuit is powered by a 24V DC source (T2) and includes various relays and contacts. Section A (left) includes a 'RISE TRK.' section with contacts 282, 283, 263, 262, 261, 259, 284, 285, 254, 270, 260, 255, and 271. It also features a 'Marg.' section with contacts 261, 259, 284, 285, 254, 270, 260, 255, and 271. A 'Rel.M.' section is connected to contacts 261, 259, 284, 285, 254, 270, 260, 255, and 271. A 'Vert.M.' section is connected to contacts 261, 259, 284, 285, 254, 270, 260, 255, and 271. Section B (right) includes a 'RISE TRK.' section with contacts 209, 204, 201, 202, 207, 208, 239, 237, 205, and 217. It also features a 'Marg.' section with contacts 209, 204, 201, 202, 207, 208, 239, 237, 205, and 217. A 'Rel.M.' section is connected to contacts 209, 204, 201, 202, 207, 208, 239, 237, 205, and 217. A 'Vert.M.' section is connected to contacts 209, 204, 201, 202, 207, 208, 239, 237, 205, and 217. The circuit also includes a 'Marg.' section with contacts 223, 224, 215, 214, 212, 225, 215, 216, and 232. A 'Rel.M.' section is connected to contacts 223, 224, 215, 214, 212, 225, 215, 216, and 232. A 'Vert.M.' section is connected to contacts 223, 224, 215, 214, 212, 225, 215, 216, and 232. The diagram uses a mix of American and British conventions for symbols, including dot notation for coil polarity and different contact representation styles.

UNITED STATES PATENT OFFICE

HERBERT M. FRIENDLY, OF CHICAGO, ILLINOIS; MILTON S. FRIENDLY AND CENTRAL TRUST COMPANY OF ILLINOIS EXECUTORS OF SAID HERBERT M. FRIENDLY, DECEASED

AUTOMATIC TELEPHONE SYSTEM

Application filed June 23, 1927. Serial No. 200,832.

Objects

The present invention is particularly directed to the switch trains used in linking connections from local subscribers' lines to local subscribers' lines and from toll operators' switchboards of the local exchange and also remote points to local subscribers' lines of said local exchange.

10 A salient feature of the present invention is the employment of a so-termed combination local and toll selector which will cooperate with a so-called combination local and toll connector or final switch. Combination local and toll connectors adapted for cooperation with antecedent local and antecedent toll selectors depending upon the origin of the call have been used heretofore and are well known. However, the combination local and toll connector of the present invention while having the general purposes of those well known incorporates details and functions which are new, so far as I am aware.

25 The employment of the combination local and toll selector of the present invention which cooperates with antecedent specific local and antecedent specific toll selectors enables selectors of a single type to be employed in a group immediately antecedent to the connectors, in place of groups of selectors which are each (group) specific to the origin of the call, as heretofore employed, so far as I am aware. The combination local and toll selector of the present invention thus admits of providing a single group of selectors, each commonly cooperative directly with the combination local and toll connectors, in place of two groups, each group specific to a certain class of calls, as heretofore employed, so far as I am aware. A smaller total number of combination local and toll selectors for cooperation with the connectors will be required under such arrangement for a given combined local and toll traffic density than if specific selectors are provided for each class of call.

30 From the last foregoing statements it will be understood that the present invention contemplates that regardless of whether the call

is progressed over the local selector train or the toll selector train it may route over the same final selector and connector in attaining connection to the called line.

Another feature of the present invention 55 is the toll operator's switching cord-pair, which provides for disconnecting or excluding the impulse calling device from the last connection progressed, automatically responsive to the completion of setting the 60 wipers of the connector upon the terminals of the called line, whether the called line is found busy and thus barred against seizure, or is found idle and in condition for seizure by the connector. 65

A feature of the toll operator's switching cord-pair is the arrangement by which through the agency of specific cord-pair ringing keys, the method of initiating ringing on the called line may be predetermined; that is, whether the called line will be rung upon intermittently automatically responsive to its seizure by the connector or whether the said character of ringing will only start at the will and under the direction of the 70 operator after the seizure of the called line by the connector. Also, that the elected predetermined method of ringing may be changed by operating the corresponding specific said key any time before or after the 75 extension of the call is started and before the called line is seized by the connector, and further, that in the event the operator has elected to have the said ringing start automatically responsive to the seizure of the 80 called line by the connector and the called line is encountered busy, preventing the seizure by the connector, the method of initiating the ringing will be thereupon changed to start only upon the will and under 85 the direction of the operator by operating the corresponding specific said key, in the event the called line becomes idle while the connector is retained in selective relation with it. 90

The toll switchboard operator will be apprised of the busy condition last referred to by means of a specific so-called busy-tone applied audible in her head telephone set (through the cord-pair listening key) and 100

also by the flashing of the cord-pair supervisory lamp. This flashing will cease when the called line becomes idle. However, the connector will not seize the selected, now idle called line under the condition unless by a directive operation by the operator for starting the ringing on the called line, which if the called line has become busy in the mean time, will operate to re-apply the said specific busy-tone and re-start the said flashing of the supervisory lamp. If the selected called line is still idle when the operator directs the starting of the ringing after the busy-tone and the flashing terminates the selected called line will be thereby seized by the connector and the ringing thereon started. The ringing on the called line is always automatically intermittent until the calling party terminates the initiated condition of the call or the called party responds. However, the frequency and inherent character of the said intermittent applications of ringing current will vary dependent upon whether the call is initiated by the local subscriber or by a toll operator. The applications of ringing current when the call is initiated by a toll operator may, as indicated, be more rapid and also may be variably spaced so that the called subscriber will be thereby apprised through the operation of a specific call bell as to the origin of the call and inspired to more hastily respond to it if it is from a toll operator.

There are a number of other features in the system believed to be novel and these will be specifically set forth in the descriptions to follow, or will be apparent in view of the descriptions.

The system chosen to elucidate the invention is only an exemplary embodiment; the invention being capable of various expressions, either as an amplification or as a curtailment, without departing from the spirit thereof, in view of the scope defined by the subjoined claims.

Drawings

With reference to the accompanying drawings:—

Fig. 1 shows a toll operator's switching cord-pair, and circuits common to a plurality of such cord-pairs as indicated by the vertical line extensions. A trunk-terminating jack J cooperative with the right-hand plug P of the cord-pair is shown on the right.

Fig. 2 shows a toll-line-terminating first selector A and a trunk-line-terminating first selector B, having common access to the toll second selector C in Fig. 3. The sheet containing Fig. 2 joins on the right of the sheet containing Fig. 1, so that the lines extending towards the adjacent margins register.

Fig. 2A shows a toll line and operator's switching-cord apparatus, the toll line extending to selector A of Fig. 2. Fig. 2A

joins above the sheet containing Fig. 2 so that the lines extending towards the adjacent margins register.

Fig. 3 shows a toll second selector C commonly accessible from the selectors A and B and other selectors of their respective groups. Fig. 3 also shows an auxiliary switch C' for causing the connector E to apply ringing current responsive to calling device impulses or a specific number of momentary interruptions of the impulse conductor. The sheet containing Fig. 3 joins on the right of the sheet containing Fig. 2 so that the lines extending towards the adjacent margins register.

Fig. 4 shows a combination local and toll third selector D which is one of a group accessible from the group containing selector C; selector D itself having access to combination local and toll connector E and others of its group. The selector D and other selectors of its group are also accessible from the group containing local second selector F. The sheet containing Fig. 4 joins above the sheet containing Fig. 3 so that the lines extending towards adjacent margins register.

Fig. 5 shows a combination local and toll connector E of which there is a group having common access to called lines. The sheet containing Fig. 5 joins to the right of the sheet containing Fig. 4 so that the lines extending toward the adjacent margins register.

Fig. 6 shows a preferred modification of selector D for use where only part (three last choice in the exemplary embodiment) of the selector group containing selector D are combination local and toll, and the balance (seven) solely local.

Fig. 7 is a diagram showing the preferred arrangement of the local and toll selector trains wherein part of the connectors (seven) are local and part (three) are combination local and toll, the preferred embodiment of the combination local and toll selectors being as shown in selector D with the disclosure in Fig. 6 introduced.

Equipment

The telephones T and T' are of the well known automatic series common-battery type.

The selector A is of the well known Strowger general class, modified in accordance with the present invention.

The selector B is of the well known Strowger general class (sometimes termed a Powell selector) modified in accordance with the present invention only as relates to the lower armature and cooperating springs and circuits including the tone source T' of the left-hand relay.

The selector C is of the well known Strowger general class, modified in accordance with the present invention. The auxiliary switch C' has the well known mechanical construc-

tion employed in so-called rotary line switches wherein the wipers are advanced upon the deenergization of the motor magnet and which has no specific idle position to which it restores.

5 The selector D is of the well known Strowger general class (sometimes termed a Powell selector), modified in accordance with the present invention only as relates to the added lower set of contacts of the left-hand relay and the added second (from the top) wiper.

10 The connector E is of the well known Strowger side-switchless combination (non-rotary) local and toll general class, modified in accordance with the present invention.

15 The line switch L may be of the well known Keith or Lamb general class, or other well known class of line switch or finder switch.

20 The local first selector M and the local second selector F may be of the well known so termed Powell type.

25 Well known switches referred to are illustrated in the third edition of Hershey's Automatic Telephone Practice as follows: Powell selector, page 60; side-switchless connector, page 38; Keith class line switch, page 45; rotary (Lamb class) line switch, page 54.

Operation

30 The operation of the system will be fully understood from exemplary descriptions of the circuit and switch operations in certain assumed calls, having in mind that where a single selector or connector is shown it is only one of a group of companion switches, since the system contemplates a plurality of like calls in simultaneous existence.

Initiating call from telephone T to telephone T'

40 Upon the calling subscriber initiating a call by removing his receiver from the switch-hook, the line switch L will operate to select the first idle first selector M. The telephone number of the called line being 11111 the calling party will first operate his calling device 10 in accordance with first digit 1 to set the first selector M into connection with the first idle second selector F. He will next operate the calling device in accordance with second digit 1 to set the second selector F in connection with first idle third selector D. He will next operate the calling device in accordance with third digit 1 to set the third selector D into connection with the first idle connector E. The operation of the switch apparatus up to this point is in accordance with well known practice, the telephone T being now connected by a clear talking path over the heavy conductors in selector D to the connector E.

45 The operation and class of the switches L, M, F and D (having in mind the stated features of selector D which belong to the present invention) will be fully understood

by reference to the said books of Hershey's as follows: line switch L, pages 41 and 53; selectors M, F and D, page 59.

50 The calling device 10 is now in series with the windings of line relay 501 over an obvious path, since the first two relays counting from the left in connector E are deactuated, and slow-releasing release relay 502 is actuated and the release trunk 505 is grounded by armature 506 to maintain the antecedent switches in seizure.

70 Responsive to the calling party sending the fourth digit 1 the relay 501 will momentarily retract its armature 508 causing ground thereon to be applied through attracted armature 509, off-normal spring 510, winding of slow-releasing series relay 512 to the vertical magnet (designated Vert. M.), causing the shaft 514 carrying the wipers 515 to 517 to be raised into alignment with the first level of bank terminals.

80 At the time the shaft 514 moves off-normal the spring 510 is disengaged and the spring 518 is connected in lieu thereof, having in mind that the armature 519 of relay 512 is now attracted. However, this armature 519 retracts consistent with the releasing characteristic of the relay 512 following the digit impulse, so that when the impulse constituting the fifth (last) digit is sent ground will be applied from armature 508, armature 509, spring 518, armatures 519, 520, 521 to the rotary magnet (designated Rot. M.), the latter magnet rotating the wipers 515 to 517 in one step into engagement with the bank terminals 525 to 527, respectively. The winding of slow-releasing relay 528 being in multiple with the winding of the rotary magnet, will operate.

90 In this connection, it will be understood that had the fourth digit been larger than 1 the armature 519 would sustain attracted until after the termination of the last impulse of the series constituting the digit, and in the same manner the armatures of relay 528 will sustain attracted until after the termination of the last impulse of the series constituting the digit. The operation of side-switchless connectors of this general class is set forth on page 36 of the before mentioned book of Hershey's.

Called line idle in call from subscriber

100 The called line being assumed idle, battery potential derived through the well known line switch cut-off relay 530 will be on bank private terminal 525 so that when armature 532 retracts a circuit path from grounded battery, winding of relay 530, terminal 525, wiper 515, make-before-break spring 531, armature 532, outside winding of wiper-switching relay 534, armature 535, make-before-break spring 536 to the grounded release trunk 505, the relay 534 actuating and locking by its inside winding through 105

armature 538 to the release trunk. The upper inside armature of relay 534 will apply busy ground over wiper 515 to terminal 525 to operate the relay 530 and guard the line called against seizure by any other connector.

Ringing called line in call from subscriber

Ringing current is now applied from grounded source R⁵, armatures 539, 540, 541, 10 542, wiper 517, bank terminal 527, bells of telephone T⁵, bank terminal 526, wiper 516, armatures 544, 545, inside winding of ring-cut-off relay 546 to grounded battery, the relay 546 not actuating from this energization 15 due to its characteristic and in view of the condensers in series with said bells. However, upon the party at telephone T⁵ responding by removing the receiver off the switchhook, causing a conductive circuit to be 20 formed over the traced path to telephone T⁵, the relay 546 will actuate and lock its inside winding through armatures 547 and 548 to the release trunk, thus completing the talking path over the heavy conductors between 25 the telephone T and T⁵. The back-bridge relay 549 will actuate and reverse the direction of current flow over the calling line responsive to the relay 546 actuating, the windings of relay 549 now being in series with the 30 telephone T⁵.

Called line busy in call from subscriber

Had the called line been busy and ground potential therefore existed on bank terminal 35 525 at the time the wiper 515 was first set thereupon the connector would not then be enabled to seize through the actuation of relay 534 because there would be no idle-battery applied over the wiper 515 to energize 40 the outside winding of relay 534. Further, the ground received over wiper 515 will be applied through spring 531, armature 532, make-before-break spring 550, armature 551 to the winding of busy relay 552, the latter 45 relay actuating and locking by its armature 535, spring 536 to the release trunk; relay 552 being disabled from deactuating until the ground is removed from the release trunk responsive to the calling subscriber hanging 50 up his receiver. During the time relay 552 is actuated specific busy tone from source B⁵ is applied interrupted through the agency of interrupter I⁵ through armatures 553 and 554 to talking conductor 555, audible to the 55 calling party.

Restoration of switches by calling subscriber

The connector and dependent antecedent switches can be restored at any time after 60 the connector is seized by the calling subscriber replacing his receiver on the switchhook to open the energizing circuit for the line relay 501, in turn causing the relay 502 to deactuate, closing the obvious circuit for 65 the release magnet (designated Rel. M.),

whereupon the shaft 514 will be restored to its normal position.

Call from toll switchboard to telephone T⁵

Upon the toll switchboard operator inserting the plug P into jack J a circuit can be traced from ground, winding of marginal relay 12, make-before-break spring 13, sleeve of plug P, sleeve of jack J, auxiliary spring 14, impulse conductor 15, armature 200 in selector B, winding of line relay 201 to grounded battery, relays 12 and 201 actuating. 70

Responsive to the actuation of relay 12 the supervisory lamp 16 will glow. Responsive to the actuation of relay 201 its dependent slow-releasing release relay 202 will actuate and apply ground from its armature 204 to the release trunk 205. However, the release trunk was previously grounded through auxiliary spring 17 at the time plug P was inserted into jack J. The guard lamp 18 will thus glow, there being a plurality of jacks similar to J and guard lamps similar to 18 (not shown) multiplied at other operators' toll switchboards. 90

Toll operator may start automatic intermittent ringing on called line

In the present call it will be assumed that the ringing on the called line will be deferred until the operator desires to start the automatic intermittent ringing. Accordingly, the specific ringing key 19 will be operated way-down and held latched in its intermediate position by the well known shift-plate 95 (not shown), however, the key plunger (not shown) is retracted far enough to disengage the way-down spring 20. Ground from spring 21 energizes relay 22. The slow-releasing relay 23 is actuated while the spring 20 is grounded to disable the shift-plate trip-magnet (designated Trip. M.) while the operator has the key 19 held manually operated way-down. The lower armature of relay 22 energizes the upper winding of slow-releasing relay 24, while the armature 25 of relay 22 applies ground through armature 26 to the winding of slow-releasing relay 27, the latter relay actuating and by its grounded armature 28 operatively energizes the relay 30 and causes it to lock to armature 25, the relay 27 deactuating consistent with its releasing characteristic. Armature 31 in attracting serves to unlock any relays corresponding to 32 of the specific operator's position which may be actuated at the time relay 27 is caused to actuate. 110

When relay 30 actuates, and after armature 28 has thereafter retracted, ground from armature 28 is applied through armature 34, spring of key 35, make-before-break spring 36, key spring 37, conductor 38 to the winding of relay 32. The latter said relay actuates and prepares a locking circuit for itself at armature 39. Due to the key 19 being locked 125 130

in its intermediate position (which it assumes when the operator removed manual pressure) by the shift-plate, the last traced circuit initially energizing the relay 32 will be maintained for the time being. The operator's impulse calling device 40 is now in a path between ground, spring 13 and the traced circuit including conductor 15, and winding of relay 201, and the relay 12 is deactuated. Lamp 16 is extinguished and operating lamp 42 is glowing.

A circuit path can now be traced from grounded battery, winding of relay 43 (which is non-susceptible to the ringing current source G') armature 44, ring of plug P and jack J, talking conductor 45, make-before-break spring 205, secondary of tone transformer T^2 to ground. Relay 43 actuates, followed by its dependent slow-releasing relay 47. Attracted armature 59 opens the ground path to key spring 37 and becomes in a locking path from armature 39 to armature 28. The operator may, by manipulating her listening key L, perceive the tone from source T^2 indicative that the calling device 40 may now be operated affective to the first selector B. A locking circuit is closed from armature 48, armature 49 to the winding of relay 30 to maintain the latter said relay actuated in the event relay 22 is deactuated, as will appear presently.

Armature 28 having retracted, its ground is applied through armatures 51 and 52 to glow the ringing lamp 53, which latter lamp is companion to the key 19 to prompt the operator that the specific key 19 was operated and that ringing on the called line will be deferred until she at will starts it by operating ringing key 55, for example. The lower winding of relay 24 is now locked through armatures 56, 59, springs 36 and 35, armatures 34 and 28 to ground.

The spring 20 being free and relay 23 being deactuated a circuit can be traced from the grounded armature 48, armatures 57 and 58 to the trip-magnet for shifting the shift-plate to release the key 19 to normal position, followed by the deactuation of relay 22. At this time relays 32, 43, 47, 24 and 30 are actuated; lamps 18, 42 and 53 are glowing and the cord-pair key 19 is in normal position.

Toll operator extends call—First digit

The operator may now operate the calling device 40 in accordance with the first digit 1 of the number of the called telephone T^s , which will cause the impulse relay 201 to correspondingly momentarily retract its armature one time, applying ground from its armature 207 through armature 208, winding of series of slow-releasing relay 209, armature 210 to the winding of the vertical magnet (designated Vert. M.), causing the shaft 212 carrying wipers 213 to 216 to be aligned with the first level of bank terminals. At the time relay 209 actuated ground from the release trunk was applied through off-normal spring 217 to operatively energize the marginal interrupter relay 220 and lock it 70 through its armature 221 to the release trunk. The relay 209 will retract its armature consistent with its releasing characteristic following the impulse (or the last impulse of a series had a series been sent) causing the 75 rotary magnet (designated Rot. M.) to be operatively energized through the off-normal spring 217, armature 221 to the release trunk. This will cause the shaft 212 to rotate the wipers 213 to 216 to set them upon the first 80 set of bank terminals 223 to 226, respectively, of the first level.

At the time the rotary magnet operated it opened the energizing path for the relay 220, causing it to deactuate and incidentally disable the rotary magnet. However, if the trunk leading to the second selector C corresponding to this set of bank terminals is busy by having been connected with by some other selector companion to first selector B 90 or selector A, its release trunk 233 and private bank terminal 223 and multiples will constitute ground potential. Under the latter condition the ground will be applied over wiper 213, armature 237, off-normal springs 95 to the winding of relay 220, the latter relay re-operating and locking to close the before stated energizing path for the rotary magnet to cause the wipers to be advanced another step, the successive advancing operations continuing so long as the wiper 213 encounters busy-ground. However, when the wiper 213 fails to receive ground potential by being set upon the private bank terminal of an idle trunk the relay 220 does 100 not then re-energize, and moreover, the lower winding of switching relay 239 is thus freed from ground potential and operatively energizes in series with the winding of unoperated relay 220 which is marginal. This continues the talking conductors from the tip and ring springs of the jack J to the conductors 231 and 232 leading-in to the toll second selector C. Relay 43 is maintained energized through armature 300 in 115 selector C to the release trunk 233. The release trunk conductor 205 and the impulse conductor 15 leading from jack J are continued to release trunk conductor 233 and to impulse conductor 234 leading-in to selector C, respectively. Relays 201 and 202 in selector B deactuate, and impulse relay 301 in selector C is operatively energized over the impulse conductor 234. Slow-releasing release relay 302 in selector C is operatively 120 energized by ground applied through retracted armature 303 and attracted armature 304. Armature 305 applies ground to the release trunk 233 before armature 204 in selector B retracts. However, ground is also applied 130

ahead on the release trunk 205 from spring 17 of the jack J.

Toll operator sends second digit

5 The operator may now operate the calling device 40 in accordance with the second digit 1 of the called telephone number which will cause relay 301 to correspondingly momentarily retract its armatures one time, applying ground from its armature 307 through armatures 308 and 309, winding of series slow-releasing relay 310 to the vertical magnet (designated Vert. M.), causing the shaft 312 carrying wipers 313 to 316 to be aligned 10 with the first level of bank terminals. At the time relay 310 actuated ground from the release trunk was applied through armature 317, off-normal springs to operatively energize the marginal interrupter relay 321 and lock it through armatures 318 and 319 15 to ground. The relay 310 will retract its armature 317 consistent with its releasing characteristic following the impulse (or the last impulse of a series had a series been sent), causing the rotary magnet (designated Rot. M.) to be operatively energized through armature 320 to the release trunk. This will cause the shaft 312 to rotate the wipers 313 to 316 to set them upon the first set of 20 bank terminals 323 to 326, respectively, of the first level.

At the time the rotary magnet operated, its armature 318 opened the energizing path for the relay 321, causing it to deactivate and 25 incidentally disable the rotary magnet. However, if the trunk leading to the third selector D corresponding to the first set of bank terminals is busy by having been connected to by some other antecedent selector companion 30 to second selector C or a selector of the group containing selector F, its release trunk 233 and the bank private terminal 323 will constitute ground potential. Under the latter assumed condition the ground will be 35 applied over wiper 313, armatures 337, 318, off-normal springs to the winding of relay 321, the latter relay operating, and locking as before to cause the wipers to be advanced another step, the successive advancing operations continuing so long as wiper 313 encounters busy-ground. However, when the wiper 313 fails to receive ground by being set upon the private bank terminal of an idle trunk the relay 321 does not re-energize, and 50 moreover, the lower winding of switching relay 338 thus is freed from ground potential and operatively energizes in series with the winding of unoperated relay 321, which is marginal.

55 This continues the talking conductors 231 and 232 through bank terminals 325 and 326 to the conductors 331 and 332, respectively, leading-in to combination local and toll third selector D. The release trunk conductor 233 and the impulse conductor 234 is continued

through bank terminals 323 and 324, conductors 333 and 334, respectively, leading-in to said selector D. The attraction of armature 308 disables the vertical magnet. The attraction of armature 339 operatively energizes slow-releasing relay 340 for an object that will appear presently. It also applies ground through armature 341 to wiper 314.

A circuit can now be traced from grounded battery, upper winding of line relay 401, 70 armature 402, talking conductor 331, bank terminal 325, wiper 315, upper secondary winding of repeating coil, armature 342, make-before-break spring 343, armature 344, outside winding of electro-polarized relay 80 345, make-before-break spring 346, armature 347, lower secondary winding of repeating coil, wiper 316, bank terminal 326, talking conductor 332, armature 403, lower winding of relay 401 to ground. The outside 85 winding of relay 345 is thus energized in the opposite polarity from that of the inside winding which inoperatively energized in series with resistor 348 when the release trunk 233 first became grounded. The relay 90 345 will therefore not actuate at this line.

Relay 401 actuates under the last described circuit condition, followed by its dependent slow-releasing relay 405, its armature 406 applying ground to the release trunk 333, so 95 that the latter conductor (release trunk) is now grounded at three points, since armature 305 in selector C is attracted and spring 17 of jack J also applies ground.

Toll operator sends third digit

100

The operator may now operate the calling device 40 in accordance with the third digit 1 of the called telephone number which will cause relay 301 to momentarily retract its 105 armatures as before, but without effect to the relay 310 since the armature 308 is attracted. However, the momentary retraction of the armature 344 in selector C will correspondingly open the traced circuit path 110 energizing the relay 401 in selector D. In view of the well known operation of the concerned circuits in selector D this will cause the shaft 412 to operate the wipers 413 to 416 into alignment with the first level of 115 bank terminals and into seized engagement with the first set of idle bank terminals 423 to 426, leading over conductors 505, 557, 558 and 559, respectively, to connector E.

In this connection, it will be noted that 120 when the switching relay 440 actuates in the well known manner, its lower armature 441, specific to the present invention, switches-through conductor 334 to wiper 414, effective for operating the converting relay 560 125 in connector E, a circuit path existing from grounded battery, winding of relay 560, conductor 557, bank terminals 424, wiper 414, armature 441, conductor 334, bank terminal 324, wiper 314, armatures 341 and 339, to 130

ground, the relay 560 actuating to convert the connector E to uses specific to calls over the toll selector train as will appear presently. However, it is pointed out that only when the selector D is seized by a toll selector as C is ground applied ahead through the armature 441 in selector D to energize relay 560 in the connector E.

The traced circuit path including the outer side winding of relay 345 in selector C, armatures 402 and 403 and relay 401 in selector D is now changed by the attraction of the latter said armatures so that wipers 415 and 416, bank terminals 425 and 426, conductors 558 and 559, make-before-break springs 561 and 562, 563 and 564 and the windings of relay 501 of connector E are now substituted for the windings of the relay 401 of selector D. Relay 501 and its dependent relay 502 20 actuate.

Toll operator sends last two digits

The connector will respond to the last two digits 11 sent by the calling device 40 in the same manner as before described with reference to the call from telephone T to the telephone T^e, but only so far as operating the vertical and rotary magnets are concerned in the actual setting of the wipers on bank terminals corresponding to the called line. Certain modified operations peculiar to toll calls will be pointed out.

At the time relay 528 actuates ground is applied through armatures 565, 566 to operatively energize the inside winding of relay 546, the latter said relay locking through its armature 547 to armature 567 (also through armature 548 to the release trunk 505 temporarily), disabling the application 40 of ringing current to the called line.

Called line encountered idle on toll operator call

If the called line is encountered idle, wherein the private terminal 525 constitutes battery potential, this will be applied through wiper 515, spring 531, armature 532, outside winding of relay 534, armature 535, spring 536, armature 568 make-before-break spring 569 to the release trunk, the relay 534 actuating and locking through its armature 538 to the release trunk. Armature 570 applies ground through make-before-break spring 571, armature 572 to the upper terminal of the upper winding of relay 549, the latter said relay actuating to reverse the direction of current in the outside winding of relay 345 in selector C, under which condition the windings of the latter said relay will energize cumulatively and operatively attract its armatures.

Excluding of calling device responsive to connector seizing

65 The attraction of armature 300 of the

relay 345 in selector C causes the toll operator's switchboard relays 43 and 47 to deactivate in sequence. The retraction of armature 59 opens the locking ground for the relays 24 and 32 and they deactivate; relay 24 deactivating last due to its releasing characteristic. The retraction of armature 48 opens the locking circuit for relay 30 and it deactuates. Lamp 42 will extinguish. Relay 12 will re-energize over the before traced path to the winding of relay 301 and lamp 16 will glow. Lamp 53 will extinguish. The eight relays of the toll operator's switchboard shown in Fig. 1 which are common to plurality of switching cord-pairs are now at 80 normal and subject to use in a new call with another cord-pair (not shown). The calling device 40 is thus excluded from the trunk circuit and the specific cord-pair responsive to the connector seizing.

85

Specific operation of connector on toll operator calls

The actuation of relay 549 completes a circuit path from ground, armatures 570, 573, 574 to the winding of slow-pick-up relay 575, the latter said relay actuating. Due to the armature 574 making last and the stated characteristic of relay 575 the relay 345 in selector C will have time to operate its armature 300 to short-circuit the resistor 348 before the windings of relay 501 are disconnected. The short-circuiting of the resistor 348 will augment the strength of current in the inside winding of relay 345 sufficiently to operatively attract its armatures even if the current in the outside winding ceases or reverses in direction before the relay has completely actuated. Relay 575 will be maintained locked through its armature 577 to the release trunk 505, which receives ground from release trunk 233, the relay 549 being incidentally deenergized by the attraction of armature 576. The relay 501 is maintained actuated by release trunk ground applied through armature 577, lower armature of relay 501 to its upper winding.

105

In view of the relay 345 in selector C being actuated, the upper and lower windings of relay 361 may be traced through armatures 367 and 368, 342 and 347, upper and lower secondary windings of the repeating coil, wipers 315 and 316, bank terminals 325 and 326, talking conductors 331 and 332, armatures 402 and 403 of selector D, wipers 415 and 416, bank terminals 425 and 426, talking conductors 558 and 559, springs 561 and 562, armatures 578 and 579, to the disengaged make contacts of armatures 545 and 541. The relay 361 is thus unenergized.

115

120

125

Starting of ringing on called line by toll operator

The toll operator can now at will start the automatic intermittent ringing of the specific

130

bell 581 of the called line by momentarily operating the ringing key 55 of her cord-pair, or alternatively by momentarily depressing key 61 three times as will appear presently.

Operating key 55 applies alternating ringing current from source G over the traced talking path including conductors 231 and 45, armature 362 and the bridged winding of relay 363 in selector C. The relay 363 which is designed to be responsive to this type of current actuates and thus causes ground from attracted armature 300 to be applied through armature 364 to the winding of slow-releasing relay 365, the latter said relay operating to open the ground from armature 339 which is applied through the wiper 314, and which said ground energizes relay 560 in the connector E. The relay 340 is thus deenergized and deactuates in accordance with its releasing characteristic. This combined operation of relays 365 and 340 causes relay 560 in connector E to momentarily deactuate, the armature 369 on relay 340 in selector C retracting to close ground from armature 339 through latter said armature to wiper 314 to thereby limit the period of deactuation of relay 560 in connector E for an object which will appear presently, regardless of how long the operator may apply the ringing current by key 55 effective to maintaining relay 365 correspondingly actuated.

Having in mind that armature 548 is now attracted, when the armature 567 momentarily retracts it unlocks the relay 546. Armature 540 being now attracted, ringing current from source G^5 is applied through interrupter armature 582, armatures 540, 541, 542, wiper 517, bank terminal 527, bell 581 of telephone T^5 , bank terminal 526, wiper 516, armatures 544, 545, inside winding of relay 546 to grounded battery, it being noted that the frequency of application of the source G^5 through the agency of interrupter I' is faster than when the source R^5 was applied through the agency of interrupter I. The source G^5 has a different frequency of alternation and other inherent characteristics, so that not only will the bell 581 of the called telephone T^5 be rung faster or at different intervals than bell 543 but the bell 581 will be rung selectively so that only one or the other bell (581 for calls from toll operator and 543 for calls from a local subscriber) will sound at any time to indicate the source of the call. That is, depending upon whether the second antecedent selector is F or C will determine which bell 543 or 581 will be rung, respectively.

60 Response on called line to toll operator call

Upon the receiver of the telephone T^5 being removed from the hook, closing a conductive circuit including the inside winding of the relay 546 the latter said relay will actuate and 65 lock through armatures 547 and 567 to

ground. This continues the talking path from armatures 545 and 541 through armatures 578 and 579 over the traced path to the upper and lower windings of relay 361 to grounded battery and ground, respectively. The relay 361 will actuate and the transmitter of telephone T^5 will be energized through its windings. The relatively low ohmic resistance involved in the winding of relay 301 in series with the impulse conductor 234 will be displaced by the relatively high ohmic resistance involved in the winding of relay 302 without lapse of current over conductor 234, due to the attraction of armatures 369 and 303, the armature 303 maintaining the relay 301 operatively energized. Due to the substitution of the winding of relay 302 for the winding of relay 301, the current traversing the winding of the relay 12 in the cord-pair is attenuated below the sustaining value so that the armature of relay 12 retracts, extinguishing the lamp 16 to indicate that the party on the called line responded.

The toll operator may now place her head telephone in talking relation with the called telephone by at will operating the listening key L and may also at will extend the talking connection by means of the plug P' and jack J' terminating the indicated line of any well known character, as a toll line or a subscriber's line, so that the cord-pair forms a talking link circuit of the connection. The talking path from the jack J' will be over the heavy conductors of the cord-pair, conductors 231 and 45 leading-out from jack J through selector B to the primary sections of the repeating coil in selector C, the armature 372 short-circuiting the condenser between the latter said windings. The talking path from the secondary sections of the said repeating coil to the called telephone has been traced. The talking circuit through the cord-pair to the called telephone T^5 , other than the repeating coil in selector C is thus clear of affecting attachments.

It will be noted, in this connection, that if the party at telephone T^5 replaces his receiver on the switch-hook the relay 361 in selector C will thereby deactuate and replace the winding of relay 301 in the impulse circuit including conductor 234, and under which condition the current traversing the winding of relay 12 will be augmented to its original operative value so that the lamp 16 will glow as a clearing signal. The toll operator may now at will re-ring on the called line as primarily, or she may alternatively restore the switches, as will appear presently.

66 Restoration of the switches by toll operator

The restoration of the switch train is made responsive to the toll operator withdrawing the plug P from the jack J. This opens the energizing circuit for relay 302, regardless of the condition of relay 361, and removes the 130

ground from the release trunk at spring 17 and at other points consistent with the de- 5 actuation of relays 302 in selector C and 502 and 560 in connector E, so that relays 338, 440 and 534 deactuate, together with obvious other relays. Selector C is restored responsive to ground being applied through armatures 307, 308 and 309, off-normal springs to the release magnet designated (Rel. M.). Se- 10 lector D is restored responsive to ground being applied through armatures 450, 451, 452, off-normal springs to the release magnet (designed Rel. M.). Connector E is restored responsive to ground being applied through 15 armatures 508, 509, off-normal springs to the release magnet (designated Rel. M.). The foregoing releasing operations will take place whether the receiver is on or off the hook of telephone T⁵.

20 *Called line encountered busy in toll operator call*

Had the called line been busy when the wipers 515 to 517 were set upon the bank terminals 525 to 527, respectively, and therefore the bank terminal 525 constituted ground potential, the busy relay 552 would actuate in the manner before described in a call from a subscriber, but due to the armature 568 being 25 attracted (only under the condition of a call by a toll operator) the latter said relay will be now locked through armature 551, spring 550, armature 535, spring 536, armature 568 and spring 569 to the release trunk. How- 30 ever, ground from armature 583 is applied through spring 571, armature 572 to the upper winding terminal of relay 549 to cause the latter relay and relay 575 to actuate and lock and relay 549 to deactuate as and for the ob- 35 jects set forth when armature 570 caused such operation. Ground from armature 565 is applied through armature 584 to the inside winding of relay 546, but to no operative ob- 40 ject since relay 546 was locked responsive to the actuation of relay 528.

45 Armature 585 attracted subsequent to the actuation and locking of the relay 552, so that in place of the latter relay being locked to the release trunk as originally, it is now locked by way of armatures 568, 585, 586, 582, spring 531, wiper 515 to the busy-grounded private terminal 525. Under the condition the interrupted ground through the tone source transformer B⁵ will be applied 50 through armatures 553, 554, and 587 to talking conductor 555 effective to periodically operate the relay 361 in selector C in correspondence with the speed of the interrupter I⁵. This will cause the cord-pair lamp 16 to 55 correspondingly flash to indicate to the operator the continued busy condition of the called line. The operator may also perceive the busy tone from source B⁵ by operating the listening key L. The operator may withdraw 60 the plug P, whereupon the switch train will

be restored in the manner before described when the plug P was withdrawn.

From the foregoing, it is clear that when a toll operator directs the setting of the connector E upon the bank terminals of a called 70 line the relay 534 will actuate to effect the seizure if it is idle, and the busy relay 552 will actuate to apply the busy signals if it is busy at the instant of selection. Moreover, only when a toll operator directs the selec- 75 tion of a called line will the relay 546 be caused to actuate and lock before the called line is selected to disable the application of ringing current thereto until ringing current is applied from the cord-pair to 80 initiate the ringing, as will appear pres- 85 ently. This application of ringing current from the cord-pair may be at will manually directed, as will first be described, or applied automatically responsive to a manual pre- setting, as will be described thereafter. Still other methods for initiating the ring- 90 ing will appear presently.

Further, it is clear that when the relay 534 actuates to effect the seizure or alternatively, 90 when the relay 552 operates to apply the busy signals, the relay 575 in the connector will be locked and the relay 32 in the cord-pair will be unlocked to exclude the calling device 40 and extinguish the lamp 42. 95

Busy called line becomes idle

If the toll operator elects to await the time when the called line will become idle, 100 she will be apprised of the idle condition by the steady glowing of the lamp 16 responsive to the busy ground on the private bank terminal changing to idle-battery potential, the relay 552 deactuating. However, there will now be no energized circuit to cause 105 the operation of relay 534 because the upper terminal of its outside winding extends through armatures 568 and 585, to retracted armature 586. That is, the connector E will not seize the now idle selected called line, so 110 that the called line is unbarred to other connectors. This is so that if the toll operator is not ready to take the line upon it becoming idle it will not be needlessly held out of service. 115

Toll operator may start ringing on selected idle called line at will

The toll operator can at will cause the 120 called line to be tested and rung upon if idle, or the busy signals applied perceptible to her if busy, responsive to momentarily applying ringing current by the key 55. This causes relay 560 to momentarily deactuate 125 as before described. However it causes different operations in the connector than before due to the fact that the relay 534 is now deactuated, whereas it actuated in the assumed call wherein the called line was se- 130

lected when idle since armature 585, now attracted, was then retracted.

The retraction of armature 567 unlocks relay 546 as before described. First assume the called line is now idle. The retraction of armature 568 causes release trunk ground to be applied through spring 536, armature 535, outside winding of relay 534, armature 532, spring 531, wiper 515 to idle battery on private terminal 525, the relay 534 actuating and locking. The attraction of armature 570 has no effective purpose at this time, since relay 575 is locked to the release trunk. The retraction of armature 567 unlocks relay 546. Ringing current from source G^5 will now be applied to the called line and the circuits are in the same condition as when the toll operator before caused it to be rung upon.

20 Selected called line again busy when toll operator attempts to start ringing thereon

Now assume that the called line is again busy when the operator attempts to start ringing thereon. When the armature 588 retracts, release trunk ground is applied through armatures 548, 588, spring 550, armature 551 to the winding of relay 552, the latter said relay actuating and locking through armature 535, spring 536 to the release trunk. When armatures 588 and 568 attract the locking circuit is changed from the release trunk to a path including armature 568, make-spring 569, armatures 585, 586, spring 531, wiper 515 to the busy-ground on the private terminal 525.

The locking circuit for relay 552 under the last described condition included the armature 586 on relay 552, and this armature retracts if the called line should again become idle, whereupon the cord-pair lamp 16 glows constantly. The operator can then at will apply ringing current by the key 55 to momentarily deactivate the relay 560 which will again cause the called line to be tested and seized by the actuation of relay 534 only if it is still idle, or alternatively cause relay 552 to again actuate if it has become busy.

10 Automatic seizure of selected called line when busy condition terminates

By closing the switch-arm 590 ground is applied to the resting contact of armature 586, and under this arrangement in case the busy condition of the selected called line terminates and the relay 552 deactuates resultant thereto a circuit is closed from ground, switch-arm 590, armature 586, spring 569, armature 568, spring 536, armature 535, outside winding of relay 534, armature 532, spring 531, wiper 515 to idle battery on private bank terminal 525. Relay 534 will actuate to effect seizure, relay 546 remaining locked. The operator can now at will un-

lock relay 546 to start ringing on the called line by operating key 55 as if the called line had been first encountered idle, since the connector is in such condition.

Object of limited retraction period of converting relay

Due to the limited retraction period of relay 560 through the agency of relay 340 in selector C the lamp 16 will be in condition to immediately flash if the selected line is not seized by the connector under conditions as have been described, even though the toll operator may still have the ringing key 55 in operated position. Of course, the relay 340 may be dispensed with if the latter operative feature is not desired.

In this connection, it will be clear that the armature 540 and cooperating contacts may be transferred to the relay 560, or even to relay 549 if the resting contact of the spring 571 is made permanently resting, without altering the operative features of the system, though false operation of the bell 543 is possible while the relay 560 is deactuated if the armature 540 is placed on the latter said relay. The brief retraction period of relay 560 will make this objection almost non-existent, and in any event if the interrupters I and I' are timed as shown in the drawings so that all rings from source R^5 will be coincident with any ringing from source G^5 , the overlapping of the false ring while armature 540 may be retracted will not be noticed.

Ringing started automatically responsive to connector seizing on toll operator calls

Had the toll operator desired to have the ringing automatically start responsive to the connector E seizing, key 65 would have been operated in place of key 19. That is, relay 66 would be operated in place of relay 22, way-down spring 67 causing relay 23 to actuate as when key 19 was operated. Under the condition of relay 66 being operated in place of relay 22, the relay 24 will not be operated. Then, when the connector is set upon the bank terminals of the called line, whether it is idle or busy, and the relays 43 and 47 thereupon deactuate in sequence, as described before, ringing current from source G' will be applied through armatures 69, 70, tip of plug P, tip of jack J and over the traced path including the bridged relay 363 in the selector C and traced path to the ring of jack J, ring of plug P, armature 44, winding of relay 43 to grounded battery, the relay 363 attracting its armature, but the relay 43 remaining deactuated due to its non-susceptibility to this ringing current. However, this circuit path will only endure until the relay 47 deactuates consistent with its releasing characteristic, to unlock the relay 32 in the manner as hereinbefore described.

This momentary actuation of the relay 363 is sufficient to cause the required momentary deactuation of relay 560 in the connector E to unlock relay 546 (which locked when relay 528 actuated) and thereby start the application of ringing current from source G⁵ to the called line. and the relay 552 (initially locked to the busy-ground) will be maintained locked to the release trunk while armature 568 is retracted. The lamp 53 will extinguish and lamp 67 will glow responsive to the operation of the key 65. 70

Operation of pre-setting cord-pair ringing keys

10. In this connection it will be clear that when the key 19 was operated way-down and released to its intermediate locked position and relay 23 has had time to deactuate consistent with its releasing characteristic, relays 43 and 47 are actuated, so that the trip-magnet will operate the shift-plate to restore the key 19; this operation of the trip-magnet occurring within a fraction of a second after the toll operator releases the depressing pressure from the key button, but long enough to insure that the key 19 was held sufficiently to permit the relay 47 to actuate. That is, the shift-plate is used only 15 to insure that the operator will not be enabled to release the key too quickly. If the operator is instructed to hold the key depressed until lamp 53 glows, sufficient time will have elapsed, and under this condition 20 the shift-plate and trip-magnet will not be required. In the same manner, the operator would be instructed to hold key 65 until the corresponding lamp 67 glows. The lamp 53 or 67 will glow until the connector seizes to 25 prompt the toll operator what kind of ringing on the called line she elected, since there are no operated keys to indicate this, and she may desire to alter this predetermined method elected in the manner as will appear 30 presently.

Changing method of initiating ringing after toll operator starts extension of call

If the toll operator when extending the 45 call after setting the key 19 to employ directed at will ringing on the called line by means of the key 55, decides to change the elected operation so the called line will be rung upon automatically responsive to the 50 connector seizing, simply depressing the key 65 at any time before the connector seizes will alter the elected predetermined condition to that indexed by the glowing lamp 53. The actuation of relay 66 will unlock relay 24 so 55 that current from source G' will be applied effective to relay 363 in selector C responsive to relay 47 deactuating responsive to the connector being set upon the terminals of the called line. This will momentarily deactu- 60 ate relay 560 in the connector to initiate the ringing on the called line if idle. However, if the called line is busy the called line will not be seized because there will be no idle battery potential on the private terminal to 65 energize the outside winding of relay 534

Had the key 65 been operated initially, in place of key 19, and under which condition the relay 24 would not be locked, the operator may change the method of ringing on 70 the called line by operating key 19 any time before the connector E is set upon the terminals of the called line. This will cause relay 24 to actuate and lock, thus preventing the application of the source G' for initiating 75 the ringing on the called line. The key 35 may also be employed to open the locking circuit of relay 24 to thereby change from deferred to automatic starting of the ring on the called line. Key 35 will also unlock re- 80 lay 32. 85

Starting ringing by control over the impulse conductor

The starting of ringing on the called line 90 in the foregoing descriptions was through the agency of ringing current applied effective to relay 363 in selector C. When the call originates over a long toll line, particularly, the applying of ringing current effective to the relay 363 may have disadvantages, or at least introduce objectional expedients. The present invention contemplates an alternative method of initiating 95 the ringing by momentarily interrupting the impulse conductor three times. The latter said arrangement permits the number of said 100 interruptions to be changed by altering the connection of a conductor of the auxiliary switch C'. 105

At the time the connector is set upon the terminals of the called line and the relay 345 thereupon actuates, a circuit is prepared from the resting contact of attracted armature 307 by the attraction of armature 375. 110 Operating key 61 three times (having in mind the calling device 40 has already been excluded) will cause three ground impulses to be applied from armature 307, armature 375, winding of series slow-releasing relay 376 to the motor magnet (designated Mot. M.), causing it to correspondingly operate three times to set the wipers 377 and 378 on bank terminals 379 and 380, respectively. Responsive to the first said impulse, the 115 armature 381 will energize the slow-releasing relay 382, and the latter two relays will sustain until after the last of the three said impulses has been sent. Thus, the wipers 377 and 378 are disconnected during their advancement. Wiper 378 becomes re-connected first and ground is thereupon applied from armature 381, wiper 378, bank terminal 380 to the winding of relay 365, the latter 120 relay actuating to momentarily open the 125

energizing circuit for relay 560 in the connector as when relay 363 operates. The armature 383 retracts consistent with the releasing characteristic of relay 382 shortly after the armature 381 retracts so that an interrupter circuit for the motor magnet is closed from grounded bank terminal 379, armature 383 to the interrupter armature of the motor magnet, the motor magnet energizing in series with the winding of relay 376 and the wipers stepping forward to dead bank terminals 384 and 385, the energization of relay 365 being brief. The wipers will rest in this position until advanced by impulses applied from armature 307. That is, four bank terminal positions constitute a set and there may be a plurality of these sets in a row of perhaps 25 terminal positions, the last bank position terminals 386 and 387 being adjacent in wiper relation to the bank terminals 388 and 389.

The relay 376 energizes and attracts its armature when the motor magnet energizes (advancing its wipers upon deenergization) so that a delay will occur after each step of the wipers when the motor magnet is operating under its own interrupter action until armature 383 retracts, since relay 382 will energize responsive to armature 381 attracting. This delay will not be objectionable since there normally would be but a single step taken and, abnormally, as by a single opening of the key 61, but three steps would be required to bring the wipers to the first successive resting position as on dead bank terminals 384 and 385, for example.

The key 61 may be operated more than three times in succession without sufficient delay between operations to admit of relay 382 deactuating causing the wipers 377 and 378 to be stepped forward accordingly and then advanced to the first successive resting position when the interruptions by the key 61 cease and armature 383 retracts.

If a single opening of the impulse conductor 234 by the operation of key 61 (or its equivalent) occurs, as by the operator withdrawing the plug P to restore the switches, the retraction of armature 307 before the retraction of armature 375 would cause a single impulse to be applied through the motor magnet to advance the wipers 377 and 378 only one step, but under this condition the relay 365 will not be energized, though the wipers will advance two steps by interrupter action to the first succeeding resting position. This last false operation of the switch C' will occur when the selector C is co-operated with an antecedent toll selector as A when the call is under control of a toll operator over a toll line, as will appear presently. This operation may occur because the relay 301 will deactuate before the ground is removed from the release trunk

by relays 302 and 502, only if the called party has first hung up.

The release trunk conductor 233 extending back to spring 17 of jack J may be disconnected without affecting the actual operation of the system in effecting conditions from jack J and its multiples (not shown), since the selector B will be maintained from ground projected from armature 305 in selector C over the release trunk to which relay 239 in selector B is energized. However, if a selector like selector B is introduced intermediate between selector B and selector C this application of ground from spring 17 of jack will be required. Under the latter condition an extra digit in the called line number corresponding to said intermediate selector will be required.

Re-ringing on called line by control over impulse conductor 85

In view of the auxiliary switch C' causing the operation of relay 560 in the connector corresponding to that effected by the operation of relay 363 in selector C, the re-ringing and re-testing operations described with reference to the application of ringing current by ringing key 55 of the cord-pair will apply equally to any operation of the auxiliary switch C' wherein wiper 378 is primarily set upon a bank terminal connected as 380 and 387.

Distant toll operator calling over toll line

In the foregoing descriptions the toll operator located contiguous to the local exchange containing the called line directed the extension of the call over a four-conductor trunk to the called line extending to telephone T⁶. The operation wherein the extension to said called line is directed from a toll operator located at a distance wherein a two-conductor toll line intervenes will be described.

The selector A is a specific incoming toll selector terminating the toll line, so designated. The remote toll operator is provided with a plurality of connecting cord-pairs, one of which having connecting plugs P² and C² is shown. These cord-pairs may have any well known circuit arrangements in addition to the circuit arrangement associated with the sleeve conductor which is specific to the present invention.

Initiation of call by distant toll operator 120

The remote toll operator will initiate the call by inserting plug P² into jack J². A circuit path can now be traced from ground, winding of polarized relay 251, make-before-break spring 252 of sending device key K², sleeve of plug P², auxiliary spring 253 (closed by reason of plug P² being in jack J²), center of line winding of repeating coil R², limbs of toll line in parallel, center of line winding of repeating coil r², winding of

line relay 254, armature 255 to battery having its positive pole grounded, the relay 251 moving its armature to cause lamp 257 to glow to indicate the impulse circuit is closed, relay 254 actuating. Slow-releasing release relay 258 will actuate from ground applied from armature 260 and armature 261 will apply ground to the release trunk 262. Armature 263 prepares a circuit for the marginal relay 265.

The remote toll operator will now operate the key K² to substitute the impulse calling device 267 for the relay 251, the lamp 257 extinguishing. The operator will now operate the sending device 267 to send one open impulse corresponding to the first digit 1 of the telephone number of the called line. Relay 254 will accordingly momentarily deactivate one time, its armature 260 sending a ground impulse through armature 270 and winding of slow-releasing series relay 271 to the vertical magnet (designated Vert. M.), causing the shaft 272 to step its wipers 273 to 276 into alignment with the first level of bank terminals. In view of the selective circuits of selector A being like those in selector B, which has been fully described, it is not thought necessary to recite the complete operation of selector A in seizing the first set 30 of idle bank terminals of the first level leading to selector C.

The switching relay 281 being now actuated, a circuit can be traced from ground, winding of marginal relay 265, armatures 263 and 282, wiper 274, bank terminal 278, impulse conductor 234 to the winding of relay 301, relays 265 and 301 actuating. Armature 283 energizes slow-releasing relay 284. It will thus appear that when the operator sends the last four digits 1111 the relays 254, 265 and 301 will correspondingly vibrate, the relay 301 causing the selectors C and D and connector E to operate in the manner before described to select the called line leading to telephone T⁶. The relay 284 will sustain its armature during the retractions of armature 283. The attraction of armature 300 will not affect the toll line beyond removing a slight unbalance due to the removal of ground from the lower talking conductor of selector A.

Called line encountered busy in call extended by distant toll operator

If the called line is encountered busy, the busy tone may be discerned by the operator listening in with her listening key (not shown), and due to the before described periodic operation of relay 361 under the busy condition the relay 265 will correspondingly vibrate its armatures due to its marginal characteristic. The periodic operations of the relay 361 under the influence of the interrupter I⁵ at the connector are slow enough to permit the relay 284 to retract its armature responsive thereto, though it will

not retract its armature responsive to the retractions of armature 283 when call directing impulses are sent from the device 267.

If the key spring 252 is restored the lamp 257 will again glow and it will appear that the lamps 286 and 257 will alternatively glow responsive to the armature 255 changing the polarity of current traversing the relay 251 to visually indicate the busy condition to the operator. This alternate flashing of the lamps 286 and 257 will cease and lamp 257 will constantly glow when the busy condition terminates. The called line can now have ringing current applied to it at will under direction of the remote toll operator.

Ringing on called line under direction of distant toll operator

The remote toll operator may now operate her sending device 267 in accordance with the digit 3, thereby causing relay 301 in selector C to correspondingly vibrate. In view of relay 345 being actuated, this will cause the auxiliary switch C' to energize relay 365 for momentarily deactuating relay 560 in the connector for the purposes before described, the called line being thus rung upon if still idle, and the busy signals re-applied if it has become busy again. The application of ringing current to the called line when idle will be the same whether it is first encountered busy or idle, since the momentary deactivation of relay 560 in the connector will not take place until the remote toll operator directly operates the calling device 267. However, ringing current applied over the toll line effective to relay 363 will have the same effect as the sending of digit 3 so far as momentarily deactuating relay 560.

Response on called line to distant toll operator call

When the called party at telephone T⁶ responds the relay 361 will actuate and steadily attenuate the current traversing the relay 265, causing the latter said relay and relay 284 to deactivate. The reversal of current polarity to relay 251 by the retraction of armature 255 causes the lamp 257 to extinguish and lamp 286 to glow. Of course, the lamp 286 may be dispensed with, and under that condition the prolonged extinguishment of lamp 257 will indicate the response on the called line. The reverse operation of relay 251 and glowing of lamp 257 will take place when the called party hangs up.

In this connection, it will be noted that when the relay 284 retracts or attracts its armature to change the polarity of current for energizing the relay 251 a lapse of current through the winding of relay 254 will occur while the armature 255 is passing from one cooperative contact to the other. However, this lapse will not be of a duration that will cause operative upset, due to intermedia-

ate relays introducing delays which will absorb the lapse before it becomes operatively effective to vitiate the call.

Restoration of the switches by the distant toll operator

The remote toll operator can at will restore the switches by withdrawing the plug P², causing the deenergization of relays 254, 10 258 and 281, and thereby closing the obvious circuit for the release magnet (designated Rel. M.) to restore selector A. The successive switches of the train will restore in the manner before described when the switches 15 were restored by the withdrawal of plug P.

Tone to apprise toll operator when connector is set upon terminals of called line

The tone source B³ is applied through armatures 391 and 392 to the lower talking conductor of selector C, audible to the toll operator, responsive to the connector being set upon the called line terminals. This tone 20 will be disconnected at armature 392 responsive to the party on the called line removing his receiver and will again be applied responsive to his hanging it up, so that audible signal to the toll operator is given as to these 25 conditions. The timing of the tone sources is such that the tone from source B³ will not be applied coincident, or at least completely coincident, with the application of the busy-tone source B⁵ so as to avoid confusion in 30 case the called line is encountered busy 35 wherein both tones will be applied. That is, tones are non-coincidentally applied with respect to the periodic applications of each said tone, effected through the interrupters I⁶ and I⁸.

40 The tone source M⁸, applied through the switch-arm 393 when the arm is set in its shown dotted position by the switch attendant, substitutes the low resistance secondary winding of the said tone source transformer 45 for the release trunk. This tone will be perceived by the toll operator as indicative that the selector C has been seized by the antecedent selector in the concerned call extension. It will be disconnected when the connector 50 is set upon the terminals of the called line at which time relay 345 actuates. The timing of this tone from source M⁸ will be consistent with the timing of tones from sources B³ and B⁵. That is, the interrupters 55 I³, B³ and IM will be mounted on the same shaft and angularly displaced with respect to each other so that each corresponding tone will be solely operative during a certain portion of a revolution. The tones from the 60 said sources B⁵, B³ and M⁸ will be distinctive in pitch or other quality.

Preferred embodiment of selector D introducing Fig. 6

65 By reference to Fig. 7 it will be noted that

the group of selectors containing selector D show their first level divided into a group of seven first choice specific local connectors of any suitable well known type, and a second group of three second choice combination local and toll connectors containing connector E. The group containing specific local selector F and the group containing specific toll selector C show their first level common to the group containing selector D. That is, the group of combination local and toll selectors containing selector D will 70 commonly serve all calls; subscriber calling or toll operator calling, whether the call is completed through a specific local connector or a combination local and toll connector as E.

The group of selectors containing selector D will contain only enough selectors to carry the required total traffic originating 85 by subscribers and toll operators and will therefore be fewer in number than if two groups were provided; one for each said class of calls. However, only a portion (3 to 7) of the connectors are combination local and toll connectors, since as will appear, the combination local and toll connectors will be sole choice for calls directed by a toll operator while these latter will be last choice for calls directed by a subscriber; all of the connectors of the two said groups being 90 available for calls directed by a subscriber.

Combination local and toll connectors are inherently more expensive and complicated than specific local connectors, so it is advantageous to employ as small number of combination local and toll connectors as will 95 safely carry the maximum toll traffic. The number of specific local connectors may therefore be less than the number estimated 100 to carry the maximum local or subscriber directed traffic, relying on converting to local traffic uses such of the combination local and toll connectors as may be required at such times of maximum local traffic and when 105 there may not be a maximum of toll traffic.

Selector D discriminates on toll operator calls

The means for causing the selectors as D to discriminate and pass over idle bank terminals corresponding to specific local connectors and seize only an idle combination local and toll connector will be pointed out.

Having in mind that the selector D referred to in Fig. 7 has the circuit modifications shown in Fig. 6 introduced, it will be clear that only when a selector as D is seized by a specific toll selector as C will ground be applied over conductor 334 cam-spring 451 to wiper 413 to place a false busy on the latter said wiper only while the wipers are passing over the first seven rotary bank positions indicated by the bracket 453, so that any idle specific local connector will be barred, and due to the cam-spring 451 being 115 120 125 130 135 140

operated to open this connection to wiper 413, by the setting of the cam 454 on the shaft 412 when the eighth bank position is reached, the false busy is removed and the 5 first idle combination local and toll connector of the three indicates by the bracket 456 will be seized.

Selector D non-discriminating in subscriber directed call

When the selector as D is seized by a selector as F the conductor 334 be free of ground potential and therefore the first idle connector; specific local or combination local and 15 toll, will be seized.

From the foregoing, it will be clear that the selectors as D incorporate the modification disclosed in Fig. 6 in the preferred embodiment wherein all the connectors are not 20 combination local and toll. That is, the selectors as D shown in Fig. 4 will be used when all connectors are combination local and toll.

It will be understood that while a level of 25 bank terminals is shown having ten sets of terminals corresponding to ten succeeding switches, the succeeding switch group may contain more than ten switches, and connections thereto lapped between the banks of 30 the antecedent switches so that all antecedent switches will not have access to all succeeding switches. Lapping of bank connections to accomplish this, in general, is not new in the art.

35 What is claimed is:—

1. In an automatic telephone system, a called line, first and second calling lines, automatic switches for linking connections from the respective calling lines to the called 40 line, a connective switch of said switches for completing connections to the called line common to connections from said calling lines to the called line, a selective switch of said switches for completing connections to the 45 connective switch common to connections from the said calling lines to the called line, specific selector switches for completing connection from the respective said calling lines to the selective switch, and means involving 50 one of said selector switches depending upon which said calling line is extended to the connective switch for determining what specific operation the connective switch will be enabled to thereafter perform.

55 2. In an automatic telephone system, a called line, first and second calling lines, automatic switches for linking connections from the respective calling lines to the called line, a connective switch of said switches for 60 completing connections to the called line common to connections from said calling lines to the called line, a selective switch of said switches for completing connections to the connective switch common to connections 65 from the said calling lines to the called line,

specific selector switches for completing connection from the respective said calling lines to the selective switch, two sources of signaling current, and means involving one of said selector switches depending upon which said calling line is extended to the called line for determining which said source of signaling current can be applied to the called line.

3. In an automatic telephone system, a called line, calling lines of two classes, a selective switch, automatic switch mechanism specific to each class of calling lines for completing connection from a random said calling line to said switch, a movable connective terminal of the switch, a group of successively positioned fixed line terminals swept by a single advance movement of said movable terminal, means for preventing said movable terminal from stopping on the terminal of a busy line, means for causing said movable terminal to stop on the fixed terminal of an idle line, and means depending upon the class of the line calling and including the corresponding said switch mechanism for causing said movable terminal to pass over other of said fixed terminals whether the corresponding line is busy or idle.

4. In an automatic telephone system, calling lines of two classes, a called line, two groups of automatic switches, each switch having direct access to the called line, a single group of automatic switches each having access to said two groups of automatic switches, switch mechanism for extending connection from the calling lines through 100 said single group to the called line wherein one of said switches of said two groups will be a link of the connection, and means involving said switch mechanism and depending upon the class of the calling line for determining that the connection to the called line may be completed through a random switch of said two groups or only through a switch of a specific one of said two groups.

5. In an automatic telephone system, calling lines of two classes, a called line, two groups of automatic switches having common access directly to the called line, a single group of automatic switches having common access to said two groups of automatic switches, switch mechanism for extending connections from the calling lines through said single group to the called line wherein one of said switches of said two groups will be a link of the connection, and means involving said switch mechanism and depending upon the class of the calling line for determining that the connection to the called line may be completed through a random switch of said two groups or only through a switch of a specific one of said two groups.

6. In a telephone system, an operator's connecting jack, an operator's connecting link co-operative with said jack, an auto- 130

matic connective switch, a trunk line connecting said jack and switch, terminals of called lines accessible from said switch, a calling device for said link, operator controlled means for connecting the calling device to said link at will, after said link has been cooperated with said jack and while the calling device is maintained in its normal resting position, means for then manually setting the calling device to thereby automatically directively set said switch into selective relation with the terminal of a random said called line, and means operated over said trunk responsive to the said setting of said switch for disconnecting the calling device from said link.

7. In a telephone system, an operator's connecting jack, an operator's connecting link co-operative with said jack, an automatic connective switch, a trunk line connecting said jack and switch, terminals of called lines accessible from said switch, means operated over the trunk line for directing the operation of said switch to select a random said called line, a visual signal device individual to said link, and means operated over a single conductor of said trunk responsive to the said selection of a said called line for visually displaying the signal device.

8. In a telephone system, a trunk line, an automatic switch terminating said trunk line, terminals of called lines accessible from said switch, a calling device, manually operated means for connecting said calling device to the trunk line, means for then manually setting said calling device to thereby automatically directively set said switch into selective relation with the terminal of a random said called line, and means operated over a single conductor of the trunk line responsive to the said setting of said switch for disconnecting the calling device from said trunk.

9. In a telephone system, a trunk line, an automatic switch terminating the trunk line, a called line accessible from the switch, means under control of an operator for directing the operation of said switch over the trunk line to extend a connection from the trunk line to the called line, a source of signaling current for application to the called line, means operated before directing the said setting of the switch to cause the signaling current to be applied to the called line responsive to said switch effecting said connection and for thereafter at will disabling the said application of signaling current after said operation of the switch has started but before its operation has been completed into connection with the called line.

10. In a telephone system, a trunk line, an automatic switch terminating the trunk line, a called line accessible from the switch, means under control of an operator for directing the operation of said switch over the

trunk line to extend a connection from the trunk line to the called line, a source of signaling current for application to the called line, means for causing the signaling current to be applied to the called line responsive to said switch effecting said connection and for thereafter at will disabling the said application of signaling current after said operation of the switch has started but before its operation has been completed into connection with the called line.

11. In a telephone system, a trunk line, an automatic switch terminating the far end of the trunk line, a source of signaling current, called lines accessible from said switch, means operated over the trunk line from the near end for operating said switch to effect a connection from the trunk line to a desired one of said called lines, and means at the near end of the trunk line operated from said switch over the trunk line to cause the signaling current to be applied to the connected called line responsive to said switch effecting said connection.

12. In a telephone system, a trunk line, an automatic switch terminating the far end of the trunk line, a movable terminal of said switch, a fixed terminal of a called line selectively accessible from said movable terminal, means for barring seizure of the fixed terminal by the movable terminal when the movable terminal is set upon the fixed terminal only if the called line is busy, means directed over the trunk line from the near end thereof for setting the movable terminal upon the fixed terminal, a visual signal device at the near end of the trunk line, and automatic means operated over the trunk line by said switch for displaying said signal device responsive to the movable terminal being set upon the fixed terminal only if the called line is busy.

13. In a telephone system, a trunk line, an automatic switch terminating the far end of the trunk line, a movable terminal of said switch, a fixed terminal of a called line selectively accessible from said movable terminal, means for barring seizure of the fixed terminal by the movable terminal when the movable terminal is set upon the fixed terminal only if the called line is busy, means directed over the trunk line from the near end thereof for setting the movable terminal upon the fixed terminal, a visual signal device at the near end of the trunk line, automatic means operated over the trunk line by said switch for displaying said signal device responsive to the movable terminal being set upon the fixed terminal only if the called line is busy, and means for disabling the display of said signal device responsive to the busy called line thereafter becoming idle.

14. In a telephone system, a trunk line, an automatic switch terminating the far end of the trunk line, a movable terminal of said

- switch, a fixed terminal of a called line selectively accessible from said movable terminal means for barring seizure of the fixed terminal by the movable terminal when the movable terminal is set upon the fixed terminal only if the called line is busy, means directed over the trunk line from the near end thereof for setting the movable terminal upon the fixed terminal, a visual signal device at the near end of the trunk line, automatic means operated over the trunk line by said switch for displaying said signal device responsive to the movable terminal being set upon the fixed terminal only if the called line is busy, means for disabling the display of said signal device responsive to the busy called line thereafter becoming idle, and means operated over the trunk line from the near end thereof for thereafter at will causing the said set movable terminal to seize the fixed terminal only if the called line is then idle.
15. In a telephone system, a trunk line, an automatic switch terminating the far end of the trunk line, a movable terminal of said switch, a fixed terminal of a called line selectively accessible from said movable terminal, means for barring seizure of the fixed terminal by the movable terminal when the movable terminal is set upon the fixed terminal only if the called line is busy, means directed over the trunk line from the near end thereof for setting the movable terminal upon the fixed terminal, a visual signal device at the near end of the trunk line, automatic means operated over the trunk line by said switch for displaying said signal device responsive to the movable terminal being set upon the fixed terminal only if the called line is busy, means for disabling the display of said signal device responsive to the busy called line thereafter becoming idle, and means operated over the trunk line from the near end thereof for thereafter at will causing the movable terminal to seize the fixed terminal only if the called line is then idle, and for again displaying said signal device if the called line is again busy when the last said means is operated.
20. In a telephone system, a trunk line, an automatic switch terminating the far end of the trunk line, a movable terminal of said switch, a fixed terminal of a called line selectively accessible from said movable terminal, means for barring seizure of the fixed terminal by the movable terminal when the movable terminal is set upon the fixed terminal only if the called line is busy, means directed over the trunk line from the near end thereof for setting the movable terminal upon the fixed terminal, a visual signal device at the near end of the trunk line, automatic means operated over the trunk line by said switch for displaying said signal device responsive to the movable terminal being set upon the fixed terminal only if the called line is busy, means for disabling the display of said signal device responsive to the busy called line thereafter becoming idle, and means for again displaying said signal device if the called line again becomes busy while the movable terminal is maintained on the fixed terminal.
25. In a telephone system, calling lines of two classes, a called line, an automatic switch common to both said classes for completing connections from said calling line to the called line, an automatic switch antecedent to first said automatic switch which is also common to all said connections, two sources of signaling current in first said switch, and automatic means for applying one or the other of said sources to the called line responsive to effecting connection thereto depending upon from which one of said classes of calling lines the connection is extended.
30. In a telephone system, calling lines of two classes, a called line, an automatic switch common to both said classes for completing connections from said calling line to the called line, an automatic switch antecedent to first said automatic switch which is also common to said connections, a battery feed to the talking conductors of first said automatic switch, and means depending upon from which one of said classes of calling lines the connection is extended for disconnecting said battery feed.
35. In a telephone system, a toll line, an automatic switch terminating the far end of the toll line, a simplex circuit derived from said toll line, a signal device at the near end of the toll line, a called line, sources of current of opposite polarities for application over said simplex circuit from the far end of the toll line, means including said switch and a single one of said sources of current directly operated over said simplex circuit from the near end for extending a connection through said switch to the called line, means responsive to the application of the other one of said sources for causing the signal device to display, and means operated over the called line for applying the other one of said sources over said simplex circuit for causing the signal device to display without destroying the connection to the called line.
40. In a telephone system, a trunk line, a selective switch on the trunk line for extending talking connections away from the trunk line, a called line accessible from the selective switch, a relay connected in bridge of the talking conductors of the trunk line, another relay adapted for being connected in bridge of the talking conductors of the trunk line antecedent to the location of first said relay on the trunk line, means controlled over the talking conductors of the trunk line for directly operating the first said relay.
45. In a telephone system, a trunk line, a selective switch on the trunk line for extending talking connections away from the trunk line, a called line accessible from the selective switch, a relay connected in bridge of the talking conductors of the trunk line, another relay adapted for being connected in bridge of the talking conductors of the trunk line antecedent to the location of first said relay on the trunk line, means controlled over the talking conductors of the trunk line for directly operating the first said relay.
50. In a telephone system, a trunk line, a selective switch on the trunk line for extending talking connections away from the trunk line, a called line accessible from the selective switch, a relay connected in bridge of the talking conductors of the trunk line, another relay adapted for being connected in bridge of the talking conductors of the trunk line antecedent to the location of first said relay on the trunk line, means controlled over the talking conductors of the trunk line for directly operating the first said relay.
55. In a telephone system, a trunk line, a selective switch on the trunk line for extending talking connections away from the trunk line, a called line accessible from the selective switch, a relay connected in bridge of the talking conductors of the trunk line, another relay adapted for being connected in bridge of the talking conductors of the trunk line antecedent to the location of first said relay on the trunk line, means controlled over the talking conductors of the trunk line for directly operating the first said relay.
60. In a telephone system, a trunk line, a selective switch on the trunk line for extending talking connections away from the trunk line, a called line accessible from the selective switch, a relay connected in bridge of the talking conductors of the trunk line, another relay adapted for being connected in bridge of the talking conductors of the trunk line antecedent to the location of first said relay on the trunk line, means controlled over the talking conductors of the trunk line for directly operating the first said relay.
65. In a telephone system, a trunk line, a selective switch on the trunk line for extending talking connections away from the trunk line, a called line accessible from the selective switch, a relay connected in bridge of the talking conductors of the trunk line, another relay adapted for being connected in bridge of the talking conductors of the trunk line antecedent to the location of first said relay on the trunk line, means controlled over the talking conductors of the trunk line for directly operating the first said relay.

to thereby operate the selective switch to select the called line, and means operated responsive to the selective operation for disconnecting the first said relay and for substituting the second said relay in bridge of the talking conductors of the trunk line at said antecedent location.

21. In a telephone system, a trunk line, an automatic switch on the trunk line, a called line accessible from the switch, means controlled over the trunk line for directly operating the switch to select the called line, a busy signaling device for sending busy signals to the trunk line, means responsive to encountering the selected called line busy for applying busy signals to the trunk line from said busy signaling device, a source of call signaling current, means responsive to encountering the selected called line idle for applying the call signaling current to the selected called line, means responsive to the encountered busy condition of the selected called line terminating for discontinuing the said applied busy signals while maintaining the selected called line idle, and means thereafter at will controlled over the trunk line for making the selected idle called line busy and for also causing the call signaling current to be thereupon applied to the selected called line.

22. In a telephone system, a trunk line, an automatic switch on the trunk line, a called line accessible from the switch, means for directly operating the switch to select the called line, a busy signaling device for sending busy signals to the trunk line, means responsive to encountering the selected called line busy for applying busy signals to the trunk line from said busy signaling device, means responsive to the encountered busy condition of the selected called line terminating for discontinuing the said applied busy signals while maintaining the selected called line idle, and means thereafter at will controlled over the trunk line for making the selected idle called line busy.

23. In a telephone system, a trunk line, an automatic switch on the trunk line, a called line accessible from the switch, means for directly operating the switch to select the called line, a busy signaling device for sending busy signals to the trunk line, means responsive to encountering the selected called line busy for applying busy signals to the trunk line from the busy signaling device, a source of call signaling current, means responsive to encountering the selected called line idle for applying the call signaling current to the selected called line, means responsive to the encountered busy condition of the selected called line terminating for discontinuing the said applied busy signals while maintaining the selected called line idle, and means thereafter at will controlled over the trunk line for making the selected

idle called line busy and for also causing the call signaling current to be thereupon applied to the selected called line, last said means involving the application of current of a character to which a condenser is transparent in bridge of the talking conductors of the trunk line.

24. In a telephone system, a trunk line, an automatic switch on the trunk line, a called line accessible from the switch, means for directly operating the switch to select the called line, a busy signaling device for sending busy signals to the trunk line, means responsive to encountering the selected called line busy for applying busy signals to the trunk line from the busy signaling device, a source of call signaling current, means responsive to encountering the selected called line idle for applying the call signaling current to the selected called line, means responsive to the encountered busy condition of the selected called line terminating for discontinuing the said applied busy signals while maintaining the selected called line idle, and means thereafter at will controlled over the trunk line for making the selected idle called line busy and for also causing the call signaling current to be thereupon applied to the selected called line, last said means involving a device for opening an energized circuit path of the trunk line and ground.

25. In a telephone system, a trunk line, an automatic switch on the trunk line, a called line accessible from the switch, means controlled over the trunk line for directing the operation of the switch to select the called line, a relay of the switch operated for effecting the seizure of the selected called line by the switch, means whereby only if the selected called line is encountered idle the relay will operate to effect the seizure of the selected called line, means whereby if the busy selected called line thereupon becomes idle the relay will remain unoperated, and means thereafter at will controlled over the trunk line for causing the operation of the relay to effect the seizure by the switch of the idle selected called line encountered busy.

26. In a telephone system, a trunk line, an automatic switch on the trunk line, a called line accessible from the switch, means controlled over the trunk line for directing the operation of the switch to select the called line, a relay of the switch operated for effecting the seizure of the selected called line by the switch, means whereby only if the selected called line is encountered idle the relay will operate to effect the seizure of the selected called line, means whereby if the busy selected called line thereupon becomes idle the relay will remain unoperated, and means thereafter at will controlled over the trunk line for causing the operation of the relay to effect the seizure by the switch of the idle selected

called line encountered busy, last said means including a device for opening an energized circuit path including a conductor of the trunk line.

27. In a telephone system, a trunk line, an automatic switch on the trunk line, a called line accessible from the switch, means controlled over the trunk line for directing the operation of the switch to select the called line, a relay of the switch operated for effecting the seizure of the selected called line by the switch, means whereby only if the selected called line is encountered idle the relay will operate to effect the seizure of the selected called line, means whereby if the busy selected called line thereupon becomes idle the relay will remain unoperated, and means thereafter at will controlled over the trunk line for causing the operation of the relay to effect the seizure by the switch of the idle selected called line encountered busy, last said means involving a source of current of a character to which a condenser is transparent applied in bridge of the trunk line talking conductors.

28. In a telephone system, a trunk line, an automatic switch on the trunk line, a called line accessible from the switch, operator controlled directive means applied over the trunk line for causing the switch to select the called line, means for applying signaling current to the selected called line only if the selected called line is encountered idle, a ring-cut-off relay operated responsive to manually directed automatic control over the selected idle called line to disable the application of signaling current to the selected called line, and means for also operating said relay to disable the application of the signaling current to the selected called line responsive to the selected called line being encountered busy.

29. In a telephone system, a trunk line, an automatic switch on the trunk line, a called line accessible from the switch, operator controlled directive means applied over the trunk line for causing the switch to select the called line, means for applying signaling current to the selected called line only if the selected called line is encountered idle, a ring-cut-off relay operated responsive to manually directed automatic control over the selected idle called line to disable the application of signaling current to the selected called line, means for also operating said relay to disable the application of the signaling current to the selected called line responsive to the selected called line being encountered busy, and operator controlled directive means applied at will over the trunk line for restoring the relay from its operated state to thereupon apply the signaling current to the said selected called line encountered busy only if the said selected called line has in the meantime become idle.

30. In a telephone system, a trunk line, an

automatic switch on the trunk line, a called line accessible from the switch, operator controlled directive means applied over the trunk line for causing the switch to select the called line, means for applying signaling current to the selected called line only if the selected called line is encountered idle, a ring-cut-off relay operated responsive to manually directed automatic control over the selected idle called line to disable the application of signaling current to the selected called line, means for also operating said relay to disable the application of the signaling current to the selected called line responsive to the selected called line being encountered busy, and operator controlled directive means applied at will over the trunk line for restoring the relay from its operated state to thereupon apply the signaling current to the said selected called line encountered busy only if the said selected called line has in the meantime become idle, last said means involving first said operator controlled means.

31. In a telephone system, a trunk line, an automatic switch on the trunk line, a called line accessible from the switch, operator controlled directive means applied over the trunk line for causing the switch to select the called line, means for applying signaling current to the selected called line only if the selected called line is encountered idle, a ring-cut-off relay operated responsive to manually directed automatic control over the selected idle called line to disable the application of signaling current to the selected called line, means for also operating said relay to disable the application of the signaling current to the selected called line responsive to the selected called line being encountered busy, and operator controlled directive means applied at will over the trunk line for restoring the relay from its operated state to thereupon apply the signaling current to the said selected called line encountered busy only if the said selected called line has in the meantime become idle, last said means involving a source of current of a character to which a condenser is transparent directly applied to the trunk line.

32. In a telephone system, a called line, a first automatic switch having selective access to the called line, a second automatic switch having selective access to the said first switch, calling lines, switch elements for extending connection from a random one of said calling lines to said second automatic switch, the calling line determining which of said elements will be employed in the extension, means thereupon operable over the said extension from the random calling line applied through the concerned said element and said second automatic switch for selectively operating said first automatic switch to select the called line, and means the operation of which is determined by the particular said

- element employed in the extension to the said first automatic switch for determining what particular variable behavior said first automatic switch will be enabled to manifest.
- 5 33. In a telephone system, a called line, a first automatic switch having selective access to the called line, a source of signaling current for application to the called line, a second automatic switch having selective access to 70
10 the said first switch, calling lines, switch elements for extending connection from a random one of said calling lines to said second automatic switch, the calling line determining which of said elements will be employed 75
15 in the extension, means thereupon operable over the said extension from the random calling line and through the concerned said element and said second automatic switch for selectively operating said first automatic 80
20 switch to select the called line, and means the operation of which is determined by the particular said element employed in the extension to the said first automatic switch for determining whether or not said source of signaling current will be applied to the selected 85
25 called line responsive to said selection.
34. In a telephone system, a called line, a first automatic switch having selective access to the called line, a plurality of sources of 90
30 different signaling current for application to the called line, a second automatic switch having selective access to the said first switch, calling lines, switch elements for extending connection from a random one of said calling 95
35 lines to said second automatic switch, the calling line determining which of said elements will be employed in the extension, means thereupon operable over the said extension from the random calling line and 100
40 through the concerned said element and said second automatic switch for selectively operating said first automatic switch to select the called line, and means the operation of which is determined by the particular said 105
45 element employed in the extension to the said first automatic switch for determining which one of said plurality of sources of signaling current will be subject to application to the selected called line.
- 50 35. In a telephone system, a called line, a first automatic switch having selective access to the called line, a second automatic switch having selective access to said first switch, calling lines, means for extending connection from the respective calling lines to the 110
55 said second switch in a different manner specific to the calling lines, means for extending connection from a random one of the calling lines to the called lines wherein the 115
60 first and second switches are links in the connection, and means depending upon from which said called line the connection is extended from for determining what behavior the said first switch will be enabled to manifest.
36. In a telephone system, a called line, a first automatic switch having selective access to the called line, a second automatic switch having access to the said first switch, a plurality of other switches having selective access to the said second switch, a plurality of leading-in paths to said second switch, means for extending connection over a random one of said plurality of paths to said second switch and for operating the latter said switch to effect connection to said first switch, means controlled over the call extension for directing the operation of the said first switch, and means depending upon the particular one of said plurality of paths to said second switch the call extension is made over for determining what behavior the said first switch will be enabled to manifest. 120

37. In a telephone system, a trunk line, a source of current for energizing a conductor of the trunk line, a switch on the trunk line, a called line accessible from the switch, automatic means for causing the switch to select the called line, means for applying signaling current to the called line, and means operated by revertive control over the trunk line responsive to the selection of the called line for operating last said means without changing the direction of energization of said conductor of the trunk line.
38. In a telephone system, a trunk line, a switch on the trunk line, a called line accessible from the switch, automatic means for causing the switch to select the called line, means for applying signaling current to the called line, and means operated by revertive control over the trunk line responsive to the selection of the called line for operating last said means, last said means including a source of current to which a condenser is transparent. 120

40. In a telephone system, a trunk line, an automatic switch on the trunk line, a plurality of operator's connecting links, a directive device common to said links, means adapted for connecting a random said link to said trunk line, a key individual to said random link, a manual means for operating and means for thereupon causing the restoration of the operated state of the key to thereby operatively connect the directive device to said random link for thereafter 120
125
130

- directing the operation of the automatic switch, and means operated over a single conductor of the trunk line responsive to predetermined operation of the directive device for disconnecting the directive device from the link to which it has been connected. 5
41. In a telephone system, a trunk line, an automatic switch on the trunk line, a plurality of operator's connecting links, a directive device common to said links, means adapted for connecting a random said link to said trunk line, a key individual to said random link, a manual means for operating and means for thereupon causing the restoration 10 of the operated state of the key to thereby operatively connect the directive device to said random link for thereafter directing the operation of the automatic switch, means for disconnecting the directive device from a link to which it is connected responsive to the said operation of the key corresponding to another said link and to thereupon connect the directive device to said another link, and means for preventing the directive device from being connected to more than one said link at any time. 15
42. In an automatic telephone system, a plurality of trunk lines, an automatic selective switch on the respective trunk lines, called lines accessible from said switches, a directive device, means for connecting the directive device to a random one of the trunk lines to thereafter selectively operate the corresponding said switch over the trunk line by the directive device to select a desired accessible called line, a signal device for indicating when the directive device is connected to the trunk line, and means for effacing the operated state of the signal device responsive to a called line becoming selected, regardless of its busy or idle condition. 20
43. In an automatic telephone system, a plurality of trunk lines, an automatic selective switch on the respective trunk lines, called lines accessible from said switches, a directive device, means for connecting the directive device to a random one of the trunk lines to thereafter selectively operate the corresponding said switch over the trunk line by the directive device to select a desired accessible called line, a signal device for indicating when the directive device is connected to the trunk line, and means for effacing the operated state of the signal device responsive to the directive device completing the selective operation regardless of the busy or idle state of the line selected responsive to said operation of the directive device. 25
44. In a telephone system, a trunk line, an automatic selective switch on the trunk line, a called line selectively accessible from the selective switch responsive to directive control over the trunk line, an operator's 30 plug and cord, a jack of the trunk line co- operative with the plug through which said plug connects to the trunk, a calling device for effecting said directive control of the selective switch, a relay individual to the plug, a key individual to said plug for operating the relay, means whereby responsive to manually operating the key at will after said plug has been connected to the jack will operate and thus lock the relay to connect the calling device to the trunk while the calling device remains in its normal resting position, and means governed by the calling device to unlock the relay to disconnect the calling device. 35
45. In a telephone system, a plurality of lines, an automatic switch on the respective said lines, a plurality of operator's cord and plug links, a jack of the respective lines cooperative with one of said plugs for extending connection from a said plug link to the line corresponding to the jack, a calling device common to said links for directing the operation of the switches, a key individual to each said link, a relay individual to each said link, means whereby responsive to manually operating the key corresponding to a said link at will after cooperating the link with a random line will thereupon operate the said relay corresponding thereto to connect the calling device to the corresponding said link and maintain last said connection, and an operator controlled key means common to the plurality of said links operative for disconnecting the calling device from a random said plug link. 40
46. In a telephone system, a trunk line, an automatic switch having movable connective terminals on the trunk line, a calling device for directly operating the movable terminals over the trunk line, means for at will manually connecting and thereafter at will disconnecting the calling device from the trunk line, fixed terminals of a called line selectively accessible from the movable terminals to connect in predetermined manner to the called line only if the called line is idle, and means operated over the trunk line whereby responsive to directly operating the movable terminals to select the fixed terminals for thereby disconnecting the calling device from the trunk line regardless of the busy or idle state of the called line, last said means including an electrically energized conductor of the trunk line and further means for effecting said energization of current without changing the direction of said energization to render said last said means effective. 45
47. In a telephone system, a trunk line, an automatic switch having movable connective terminals on the trunk line, a calling device for directly operating the movable terminals over the trunk line, means for at will manually connecting and thereafter at will disconnecting the calling device from the trunk line, fixed terminals of a called line 50

selectively accessible from the movable terminals to connect in predetermined manner to the called line only if the called line is idle, and means operated over the trunk line whereby responsive to directly operating the movable terminals to select the fixed terminals for thereby disconnecting the calling device from the trunk line regardless of the busy or idle state of the called line, last 10 said means involving the sustained opening of an energized conductor of the trunk line.

48. In a telephone system, a trunk line, a selective switch on the trunk line, a called line accessible from the switch, a pair of talking conductors of said trunk line, a line relay energized in bridge of the talking conductors of the trunk line, two routes over which the talking conductors of said switch can be reached from different corresponding calling lines, respectively, switch mechanism specific for each said route for effecting connection from the respective calling lines to the talking conductors of the selective switch, means including said relay operated in said 25 bridge for directly operating the selective switch over the said connections alternatively to extend connection from the respective calling lines to the called line, and means depending upon the particular line calling and 30 the corresponding switch mechanism used in linking connection to the selective switch for rendering the relay disconnected from the talking conductors while the selective switch is thereafter indefinitely maintained in selective relation to the selected called line.

49. In a telephone system, a local calling line, a toll calling line, a combination local and toll connector, a called line, a leading-in trunk line, connective terminals for said 40 trunk line, a pair of talking conductors of the trunk line, a line relay in bridge of the talking conductors, means for alternatively extending the calling lines to the same said terminals and for thereafter operating the 45 relay over the talking conductors to cause the switch to extend connection from the connected calling line to the called line, and means depending upon that if the toll calling line is the one connected to the said terminals 50 for causing the line relay to be disconnected from its bridged connection without restoring the operated state of the switch with respect to the called line.

50. In a telephone system, a local calling line, a toll calling line, a combination local and toll connector, a called line, a leading-in trunk line, connective terminals for said 55 trunk line, a pair of talking conductors of the trunk line, a line relay in bridge of the 60 talking conductors, means for alternatively extending the calling lines to the same said terminals and for thereafter operating the relay over the talking conductors to cause the switch to extend connection from the connected calling line to the called line, and 65

means depending upon that if the toll calling line is the one connected to the said terminals for causing the line relay to be disconnected from its bridged connection without restoring the operated state of the 70 switch with respect to the called line, so that a clear talking path will exist through the connector on talking connections from the toll calling line to the called line although the said talking path was affected by a 75 bridged path while being operated into selective relation with the called line and so that the line relay will be bridged between the talking path on talking connections from the local calling line to the called line.

51. In an automatic telephone system, a trunk line, a selective switch on the trunk line, a called line accessible from the switch, a pair of talking conductors of said trunk line, a line relay energized in bridge of the 85 talking conductors of the trunk line, a switch for connection to the talking conductors, other switches used alternatively in extending connection to the latter said switch, means for first operating one of said other switches and thereafter the second said switch to extend connection to the selective switch and for thereafter operating the selective switch by said line relay over the talking conductors to extend connection through the operated 90 switches to the called line, and means depending upon the particular said other switch employed in the connection for determining that the line relay will thereafter be subject to deenergization while the selective switch is thereafter maintained indefinitely in selective relation to the selected called line.

52. In an automatic telephone system, a trunk line, a selective switch on the trunk line, a called line accessible from the switch, a pair of talking conductors of said trunk line, a line relay energized in bridge of the talking conductors of the trunk line, a switch for connection to the talking conductors, other switches used alternatively in extending connection to the latter said switch, means for first operating one of said other switches and thereafter the second said switch to extend connection to the selective switch and for thereafter operating the selective switch by said line relay over the talking conductors to extend connection through the operated switches to the called line, and means depending upon the particular said other switch employed in the connection for determining that the line relay will be deenergized responsive to the selection of the called line while the selective switch is thereafter indefinitely maintained in selective relation to the selected 105 called line.

53. In a telephone system, a trunk line, connecting terminals of the trunk line for receiving connection to the trunk line, a selective switch on the trunk line for extending talking connection away from the trunk line,

5 a front-bridge relay and a back-bridge relay for the talking path of the selective switch, a plurality of routes over which connection to the same said connecting terminals can be effected, and means depending upon the one of said routes used for causing the said relays to be disconnected from the talking path while the path is used as a link of a talking connection.

10 54. In a telephone system, a trunk line, connecting terminals of the trunk line for receiving connection to the trunk line, a called line, a selective switch on the trunk line for extending talking connection away from the 15 trunk line to the called line, a back-bridge relay for the talking path of the selective switch for supplying current over the connected called line, a plurality of routes over which connection to the same said connecting terminals 20 can be effected, and means operated depending upon the said route used to said terminals for causing the said relay to be disconnected from the talking path and another back-bridge relay for the talking path thereupon 25 substituted on the talking path antecedent to said connecting terminals.

55. In a telephone system, a trunk line, connecting terminals of the trunk line for receiving connection to the trunk line, a called 30 line, a selective switch on the trunk line for extending talking connection away from the trunk line to the called line, a back-bridge relay for the talking path of the selective switch for supplying current over the connected called line, a plurality of routes over 35 which connection to the same said connecting terminals can be effected, means operated depending upon the said route used to said terminals for causing the said relay to be disconnected from the talking path and another back-bridge relay for the talking path thereupon 40 substituted on the talking path antecedent to said connecting terminals, and means for applying a signal to the antecedent 45 connection to indicate that the last said means has operated.

56. In a telephone system, a trunk line, an 50 automatic wiper switch on the trunk line, a level of line bank terminals accessible from the wiper, means for directing the operation of the wiper over the trunk line to align the wiper with the level, automatic means responsive to said operation for causing the wiper to sweep the level and stop its operation 55 responsive to encountering the first idle bank level line terminal, means controlled over the trunk line for preventing the wiper from stopping responsive to encountering an idle said terminal, and automatic means controlled 60 by the advance movement of the wiper in sweeping the said level for disabling the last said means responsive to a predetermined advancement of the wiper.

57. In a telephone system, a trunk line, an 65 automatic wiper switch on the trunk line,

a level of line bank terminals accessible from the wiper, means for directing the operation of the wiper over the trunk line to align the wiper with the level, automatic means responsive to said operation for causing the wiper to sweep the level and stop its operation responsive to encountering the first idle bank level line terminal, means controlled over the trunk line for preventing the wiper from stopping responsive to encountering an idle said terminal, and automatic means made operative to disable the last said means responsive to the wiper having passed over a predetermined number of said terminals.

58. In a telephone system, a trunk line, an 70 automatic wiper switch on the trunk line, a level of line bank terminals accessible from the wiper, means for directing the operation of the wiper over the trunk line to align the wiper with the level, a plurality of automatic 75 switches having access to the trunk line, automatic means responsive to said operation for causing the wiper to sweep the level and stop its operation responsive to encountering the first idle bank level line terminal, means controlled 80 over the trunk line and dependent upon the particular one of said plurality of switches employed in the connection to first said switch for preventing the wiper from stopping responsive to encountering an idle 85 said terminal, and automatic means controlled by the advance movement of the wiper in sweeping the said level for disabling the last said means responsive to a predetermined advancement of the wiper.

59. In a telephone system, a trunk line, an 90 automatic wiper switch on the trunk line, a level of line bank terminals accessible from the wiper, means for directing the operation of the wiper over the trunk line to align the wiper with the level, a plurality of automatic 95 switches having access to the trunk line, automatic means responsive to said operation for causing the wiper to sweep the level and stop its operation responsive to encountering the first idle bank level line terminal, means controlled over the trunk line and dependent upon the particular one of said plurality of switches employed in the connection to first said switch for preventing the wiper from stopping responsive to encountering an idle 100 said terminal, last said means involving a conductor of the trunk line specific to use with last said switch with respect to other second said switches, and automatic means controlled by the advance movement of the wiper in sweeping the said level for disabling the last said means responsive to a predetermined advancement of the wiper.

60. In a telephone system, a first automatic 105 selective switch, a main group of successively positioned second automatic switches, said group successively divided into first and second choice sub-groups, a third and a fourth switch, means for extending connection from 110

one or the other of last said switches to said first switch, means for then directively operating said first switch over the connection to select said main group, automatic means operated responsive to said directive operation for causing the connection to be further extended to the first idle said second switch and wherein the busy said second switches are barred against connection thereto, and means depending upon whether said third or said fourth switch was used in effecting connection to said first switch for determining whether both said sub-groups will be subject to connection to by said first switch responsive to said directive operation of said first switch or whether only said second choice sub-group will be subject to connection to by said first switch responsive to said directive operation of said first switch, regardless of the busy or idle state of said second switches of said first choice group.

61. In a telephone system, a trunk line, an automatic wiper selective switch on the trunk line, fixed terminals of a main group of lines adapted to be swept by the wiper, said main group being divided into a plurality of sub-groups, calling lines of a plurality of classes, switch mechanism specific to each class for extending connection from a random one of said calling lines to the selective switch, means operated over the particular calling line and corresponding said mechanism for directing the operation of the wiper to select the main group, automatic means for thereupon causing the wiper to move with respect to the terminals of the main group and to pass over the respective terminals thereof only if the corresponding line is busy, means for causing the wiper to stop upon the terminal of the first idle line encountered, and means depending upon the class of the calling line gaining connection to the trunk line for preventing the wiper from stopping upon the encountered terminal of a line of a predetermined said sub-group regardless of the busy or idle state of the lines thereof.

62. In a telephone system, a trunk line, an automatic wiper selective switch on the trunk line, fixed terminals of a main group of lines adapted to be swept by the wiper, said main group being divided into a plurality of sub-groups, calling lines of a plurality of classes, switch mechanism specific to each class for extending connection from a random one of said calling lines to the selective switch, means operated over the particular calling line and corresponding said mechanism for directing the operation of the wiper to select the main group, automatic means for thereupon causing the wiper to move with respect to the terminals of the main group and to pass over the respective terminals thereof only if the corresponding line is busy, means for causing the wiper to stop upon the terminal of the first idle line encountered, and

means depending upon the class of the calling line gaining connection to the trunk line for controlling the wiper in such manner as to disable it for stopping on other than a terminal of an idle line in a predetermined said sub-group corresponding to the group to which the calling line belongs.

63. In a telephone system, a trunk line, an automatic wiper selective switch on the trunk line, fixed terminals of a main group of lines adapted to be swept by the wiper, said main group being divided into a plurality of sub-groups, means for extending different kinds of connections to the trunk line, means for directing the operation of the switch over the connection to the trunk line to move the wiper into selective relation to said main group of lines, automatic means for thereupon causing the wiper to move with respect to the terminals of the main group and pass over the respective terminals thereof only if the corresponding line is busy, means for causing the wiper to stop upon the terminal of the first idle line of the main group encountered, a conductor leading-in to said switch, and means controlled over said conductor on only certain kind of said connections for preventing the wiper from stopping upon the encountered terminal of a line of a predetermined sub-group regardless of the busy or idle state of the lines thereof.

64. In a telephone system, a trunk line, an automatic wiper selective switch on the trunk line, a group of successively positioned line terminals accessible from the wiper, means for directively operating the wiper over the trunk line to select the group, automatic means responsive to selecting the group to cause the wiper to sweep the group of line terminals while passing over terminals of busy lines and stopping upon the first idle line terminal encountered, means for extending connection to the trunk line over a plurality of paths, and means depending upon the path used for rendering all or only certain part of the terminals of idle lines of the group subject to being stopped upon by the wiper regardless of the fact the lines of the group may all be idle.

65. In a telephone system, a trunk line, an automatic wiper selective switch on the trunk line, a group of line terminals engageable from the wiper, means for automatically operating the wiper to select the group, means for making the respective lines of the group busy, means for causing the switch to seize the engaged terminal of an idle line, means for preventing the said seizure if the line of the engaged terminal is busy, means for extending connection to the trunk line over a plurality of paths, and means depending upon the path used for rendering certain of the terminals barred from seizure although

the respective lines corresponding thereto may be idle.

66. In a telephone system, a trunk line, an automatic selective switch on the trunk line, a main group of lines accessible from the switch, said group having a sub-group of said main group, calling lines of a plurality of classes having access to the switch via the trunk line, means for extending connection from a random one of said calling lines to the trunk line, means for then automatically operating the switch to select said main group, and means whereby the calling lines of a particular one of said classes can only be extended away from said switch over the sub-group of the selected main group.

67. In a telephone system, a trunk line, an automatic selective switch on the trunk line, a main group of lines accessible from the switch, said group having a sub-group of said main group, calling lines of a plurality of classes having access to the switch via the trunk line, means for extending connection from a random one of said calling lines to the trunk line, means for then automatically operating the switch to select said main group, means whereby the calling lines of a particular one of said classes can only be extended away from said switch over the sub-group of the selected main group, and means whereby the calling lines of another of said classes may be extended away from said switch over a random line of the selected main group including the sub-group.

68. In an automatic telephone system, a trunk line and terminating automatic switch mechanism at the far end of the trunk line, an operator's switching link for cooperation with the near end of the trunk line, a relay in said link energized over a path including a talking conductor of said trunk line, a called line accessible from said switch mechanism, means operated responsive to said switch mechanism connecting to the called line for deenergizing the relay for momentarily applying said source over the trunk line from said link while the relay is deenergized.

69. In an automatic telephone system, a trunk line and terminating automatic switch mechanism at the far end of the trunk line, an operator's switching link for cooperation with the near end of the trunk line, a called line accessible from said switch mechanism, means operated over a single conductor of the trunk line responsive to said switch mechanism connecting to the called line for momentarily applying said source over the trunk line from said link.

70. In an automatic telephone system, a trunk line and terminating automatic switch mechanism at the far end of the trunk line, an operator's switching link for cooperation with the near end of the trunk line, a relay for said link, a called line accessible from said

switch mechanism, means operated responsive to said switch mechanism connecting to the called line for causing the relay to operatively attract its armature, and means controlled over the called line for retracting the armature of said relay.

71. In an automatic telephone system, a trunk line and terminating automatic switch mechanism at the far end of the trunk line, an operator's switching link for cooperation with the near end of the trunk line, a called line accessible from said switch mechanism, means operated over a single conductor of the trunk line responsive to said switch mechanism connecting to the called line for energizing the relay, and means operated over the called line and over a different single conductor of the trunk line for vibrating said relay.

72. In an automatic telephone system, a calling line, a called line, a plurality of automatic switches for extending a tandem connection by the switches from the calling line to the terminals of the called line, means for placing a busy bar potential on a terminal of the called line to prevent effecting a talking connection to the connected to called line, a tone source, and a relay in a switch antecedent to the last switch of the connection operated responsive to operating the last switch of the tandem connection into connection with the terminals of the called line for applying said tone source audible on the calling line, regardless of whether the said bar potential is on the terminal.

73. In an automatic telephone system, a calling line, a called line, a plurality of automatic switches for extending a tandem connection by the switches from the calling line to the terminals of the called line, means for placing a busy bar potential on a terminal of the called line to prevent effecting a talking connection to the connected to called line, a tone source, a relay in a switch antecedent to the last switch of the connection operated responsive to operating the last switch of the tandem connection into connection with the terminals of the called line for applying said tone source audible on the calling line, regardless of whether the said bar potential is on the terminal, and automatic means for also signaling in a distinctive manner to the calling line responsive to the busy bar potential being encountered.

74. In an automatic telephone system, a calling line, a called line, a plurality of automatic switches for extending a tandem connection by the switches from the calling line to the terminals of the called line, means for placing a busy bar potential on a terminal of the called line to prevent effecting a talking connection to the connected to called line, a tone source, a relay in a switch antecedent to the last switch of the connection operated responsive to operating the last switch

of the tandem connection into connection with the terminals of the called line for applying said tone source audible on the calling line, regardless of whether the said bar potential is on the terminal, and means operated over the called line for reconnecting the tone source to the calling line.

75. In an automatic telephone system, a calling line, a called line, a plurality of automatic switches for extending a tandem connection by the switches from the calling line to the terminals of the called line, means for placing a busy bar potential on a terminal of the called line to prevent effecting a talking connection to the connected to called line, a tone source, a relay in a switch antecedent to the last switch of the connection operated responsive to operating the last switch of the tandem connection into connection with the terminals of the called line for applying said tone source audible on the calling line, regardless of whether the said bar potential is on the terminal, and means operated over the called line for disconnecting the tone source from the calling line.

76. In an automatic telephone system, a calling line, a called line, switch mechanism for extending connection from the calling line to the terminals of the called line, means for placing a busy bar potential on a terminal of the called line to prevent effecting a talking connection to the connected to called line, a tone source, and means operated responsive to operating the switch mechanism into connection with the terminals of the called line for applying said tone source audible on the calling line, regardless of whether the said bar potential exists on the terminal.

77. In an automatic telephone system, a calling line, a called line, switch mechanism for extending connection from the calling line to the terminals of the called line, means for placing a busy bar potential on a terminal of the called line to prevent effecting a talking connection to the connected to called line, a tone source, means operated responsive to operating the switch mechanism into connection with the terminals of the called line for applying said tone source audible on the calling line, regardless of whether the said bar potential exists on the terminal, and automatic means for also signaling in a distinctive manner to the calling line responsive to the busy bar potential being encountered.

78. In an automatic telephone system, a calling line, a called line, switch mechanism for extending connection from the calling line to the terminals of the called line, means for placing a busy bar potential on a terminal of the called line to prevent effecting a talking connection to the connected to called line, a tone source, means operated responsive to operating the switch mechanism into connection with the terminals of the

called line for applying said tone source audible on the calling line, regardless of whether the said bar potential exists on the terminal, and means operated over the called line for disconnecting the tone source from the calling line.

79. In an automatic telephone system, a calling line, a called line, switch mechanism for extending connection from the calling line to the terminals of the called line, means for placing a busy bar potential on a terminal of the called line to prevent effecting a talking connection to the connected to called line, a tone source, means operated responsive to operating the switch mechanism into connection with the terminals of the called line for applying said tone source audible on the calling line, regardless of whether the said bar potential exists on the terminal, and means operated over the called line for reconnecting the tone source to the calling line.

80. In an automatic telephone system, a calling line, switch mechanism for extending connection from the calling line to the terminals of the called line, means for placing a busy bar potential on a terminal of the called line to prevent effecting a talking connection to the connected to called line, and means operated responsive to operating the switch mechanism into connection with the terminals of the called line for manifesting a signal on the calling line regardless of whether the said potential exists on the terminal.

81. In an automatic telephone system, a calling line, switch mechanism for extending connection from the calling line to the terminals of the called line, means for placing a busy bar potential on a terminal of the called line to prevent effecting a talking connection to the connected to called line, means operated responsive to operating the switch mechanism into connection with the terminals of the called line for manifesting a signal on the calling line regardless of whether the said potential exists on the terminal, and means operated over the called line for effacing the manifested state of the signal.

82. In an automatic telephone system, a calling line, switch mechanism for extending connection from the calling line to the terminals of the called line, means for placing a busy bar potential on a terminal of the called line to prevent effecting a talking connection to the connected to called line, means operated responsive to operating the switch mechanism into connection with the terminals of the called line for manifesting a signal on the calling line regardless of whether the said potential exists on the terminal, and means operated over the called line for restoring the manifested state of the signal.

83. In a telephone system, a calling line, a called line, automatic switch mechanism for extending connection from the calling line to

the called line, a bar terminal of the called line for preventing a talking connection being established to the called line, and means operated at will from the calling line after connection has been established from the calling line to the terminals of the called line for sending a signal to the calling line indicative of the barred condition only if the barred condition then exists.

10 84. In an automatic telephone system, a calling line, a called line, a plurality of automatic switches for extending a tandem connection by the switches from the calling line to the terminals of the called line, two tone sources, means for applying one of said sources to the calling line responsive to extending the connection to the next to last switch of the train, and means for applying the other of said tone sources to the calling line, in lieu of the first applied source, responsive to the last switch of the train connecting to the terminals of the called line.

15 85. In an automatic telephone system, a calling line, a called line, a plurality of automatic switches for extending a tandem connection by the switches from the calling line to the terminals of the called line, two tone sources, means for applying one of said sources to the calling line responsive to extending the connection to the next to last switch of the train, and means for applying the other of said tone sources to the calling line, from a point antecedent to the last switch of the train, in lieu of the first said applied 20 source, responsive to the last switch of the train connecting to the terminals of the called line.

25 86. In an automatic telephone system, a plurality of switches for extending a connection from the calling station to a called line, a calling device for automatically successively operating said switches to effect said connection, and means for annexing a series of impulses by the calling device to operate a 30 relay in the last switch of the connection to thereby initiate the sustained successive application of signaling current to the called line.

35 87. In an automatic telephone system, a plurality of switches for extending a connection from the calling station to a called line, a calling device for automatically successively operating said switches to effect said connection, and means for annexing only a certain predetermined series of impulses by the calling device to operate a relay in the last switch of the connection to thereby initiate the sustained successive application of signaling current to the called line.

40 88. In witness whereof, I hereunto subscribe my name this 17th day of June, 1927.

HERBERT M. FRIENDLY.

DISCLAIMER

1,800,787.—*Herbert M. Friendly*, Chicago, Ill. AUTOMATIC TELEPHONE SYSTEM. Patent dated April 14, 1931. Disclaimer filed October 9, 1933, by *Milton S. Friendly* and *Central Republic Trust Company*, as co-executors of the estate of *Herbert M. Friendly*, deceased.

Hereby enter this disclaimer to the claims in said specification which is in the following words, to wit:

“1. In an automatic telephone system, a called line, first and second calling lines, automatic switches for linking connections from the respective calling lines to the called line, a connective switch of said switches for completing connections to the called line common to connections from said calling lines to the called line, a selective switch of said switches for completing connections to the connective switch common to connections from the said calling lines to the called line, specific selector switches for completing connection from the respective said calling lines to the selective switch, and means involving one of said selector switches depending upon which said calling line is extended to the connective switch for determining what specific operation the connective switch will be enabled to thereafter perform.”

“20. In a telephone system, a trunk line, a selective switch on the trunk line for extending talking connections away from the trunk line, a called line accessible from the selective switch, a relay connected in bridge of the talking conductors of the trunk line, another relay adapted for being connected in bridge of the talking conductors of the trunk line antecedent to the location of first said relay on the trunk line, means controlled over the talking conductors of the trunk line for directly operating the first said relay to thereby operate the selective switch to select the called line, and means operated responsive to the selective operation for disconnecting the first said relay and for substituting the second said relay in bridge of the talking conductors of the trunk line at said antecedent location.”

“32. In a telephone system, a called line, a first automatic switch having selective access to the called line, a second automatic switch having selective access to the said first switch, calling lines, switch elements for extending connection from a random one of said calling lines to said second automatic switch, the calling line determining which of said elements will be employed in the extension, means thereupon operable over the said extension from the random calling line applied through the concerned said element and said second automatic switch for selectively operating said first automatic switch to select the called line, and means the operation of which is determined by the particular said element employed in the extension to the said first automatic switch for determining what particular variable behavior said first automatic switch will be enabled to manifest.

“33. In a telephone system, a called line, a first automatic switch having selective access to the called line, a source of signalling current for application to the called line, a second automatic switch having selective access to the said first switch, calling lines, switch elements for extending connection from a random one of said calling lines to said second automatic switch, the calling line determining which of said elements will be employed in the extension, means thereupon operable over the said extension from the random calling line and through the concerned said element and said second automatic switch for selectively operating said first automatic switch to select the called line, and means the operation of which is determined by the particular said element employed in the extension to the said first automatic switch for determining whether or not said source of signaling current will be applied to the selected called line responsive to said selection.”

“35. In a telephone system, a called line a first automatic switch having selective access to the called line, a second automatic switch having selective access to said first switch, calling lines, means for extending connection from the respective calling lines to the said second switch in a different manner specific to the calling lines, means for extending connection from a random one of the calling lines to the called lines wherein the first and second switches are links in the connection, and means depending upon from which said called line the connection is extended from for determining what behavior the said first switch will be enabled to manifest.

“36. In a telephone system, a called line, a first automatic switch having selective access to the called line, a second automatic switch having access to the said first switch, a plurality of other switches having selective access to the said second switch, a plurality of leading-in paths to said second switch, means for extending connection over a random one of said plurality of paths to said second switch and for operating the latter said switch to effect connection to said first switch, means controlled over the call extension for directing the operation of the said first switch, and means depending upon the particular one of said plurality of paths to said second switch the

call extension is made over for determining what behavior the said first switch will be enabled to manifest."

"70. In an automatic telephone system, a trunk line and terminating automatic switch mechanism at the far end of the trunk line, an operator's switching link for cooperation with the near end of the trunk line, a relay for said link, a called line accessible from said switch mechanism, means operated responsive to said switch mechanism connecting to the called line for causing the relay to operatively attract its armature, and means controlled over the called line for retracting the armature of said relay."

"80. In an automatic telephone system, a calling line, switch mechanism for extending connection from the calling line to the terminals of the called line, means for placing a busy bar potential on a terminal of the called line to prevent effecting a talking connection to the connected to called line, and means operated responsive to operating the switch mechanism into connection with the terminals of the called line for manifesting a signal on the calling line regardless of whether the said potential exists on the terminal."
